PACKAGING MACHINE

Kenneth F. Newell, Longmeadow, Francis Crescenzo, Springfield, Earle M. Chase, Wilbraham, and Carl E. Mehlhorn, Springfield, Mass., assignors to Package Machinery Company, East Longmeadow, Mass., a corporation of Massachusetts

Filed Dec. 4, 1959, Ser. No. 857,324
77 Claims. (Cl. 53—182)

The present invention relates to improvements in packaging machines, and more particularly to improved mechanism for forming pillow-shaped packages.

Prior machines for producing pillow-shaped packages are exemplified in U.S. Patent No. 1,986,422. These prior machines are based on the use of a pair of draw bars mounted on posts for vertical reciprocating movement. The draw bars grip a tube of wrapper material and heat-seal it along a transverse seam; the product to be packaged is dropped into the wrapper tube as it is drawn down and sealed by the draw bar. As the wrapper tube is so drawn, a knife is actuated to sever the tube intermediate the heat-sealed portion, thus completing a previously filled package. The draw bars are then opened and the completed package released. The draw bars then move upwardly and again grip the wrapper tube at the top of their stroke and repeat the same cycle of operation over and over to form pillow-shaped packages.

The object of the present invention is to simplify and make more economical the construction and operation of machines for producing packages from a wrapper tube. The inventive concepts and features devised in attaining these ends are advantageously employed in a "vertical flow" machine of the type described but are not necessarily limited to such environment in all their aspects of utility.

Another object of the invention is to facilitate the changeover from forming one size and then another size package and also to facilitate changing from the use of one wrapper material and then another wrapper material and at the same time to overcome certain heat-sealing problems which are unique to polyethylene film and like materials.

A further object of the invention is to obtain improved control over the intermittently fed wrapper web so as to match the increased operating rate of the present machine without danger of breaking or otherwise damaging the wrapper web.

Yet another object of the invention is to combine mechanical and fluid power for operating the draw bars of such machines faster and more economically.

In one aspect the invention is characterized by a linkage arrangement for mounting the draw bars of a packaging machine and constraining the movement of said draw bars to a substantially straight line path when the draw bars are in a closed gripping position and then returning the draw bars back towards the start of said straight line path of movement when the draw bars are open. Preferably the draw bars are mounted on a bracket to which the linkage means are connected and a fluid motor is mounted on the bracket to move the draw bars relative to each other between their open position and their closed gripping position.

In other aspects the inventive concepts are characterized by structure which permits rapid adjustment of the drawing out stroke of the draw bars, the extent to which they are opened, the rate of operation of the machine, and particularly the coordination of the fluid and mechanical power means employed to operate the draw bars. Additionally, structure is provided which enables the diameter of the tube of wrapping material forming the

2

package to be conveniently changed from one size to another. Further, the draw bars are mounted on cantilever rods which enable their ready replacement for repair, changes in size, or changes in wrapper materials for the packages. In this connection there will be found draw bars, particularly suited for forming packages from polyethylene web, which are characterized by the provision of means for relieving tension in the polyethylene material during the heat-sealing operation, and also improved means for longitudinally seaming a wrapper tube of polyethylene film.

Further features also involve the control and feeding of the web of wrapper material from a supply roll to the means for forming a tube of wrapper material.

15 The above and other related objects and features of the invention will be apparent from a reading of the following description of the disclosure found in the accompanying drawings and the novelty thereof pointed out in the appended claims.

20 In the drawings:

FIG. 1 is a side elevation, somewhat diagrammatical in form, showing the general organization of a packaging machine embodying the present invention;

FIG. 2 is a view taken on line II—II in FIG. 1 of draw bars and mounting means therefor, shown on an enlarged scale;

FIG. 3 is a section taken on line III—III in FIG. 2;

FIG. 4 is a plan view, with certain parts rotated to new positions, and on an enlarged scale, taken on line 30 IV—IV in FIG. 1 of crank means for imparting to and fro movement to the draw bars;

FIG. 5 is a section taken on line V—V in FIG. 4;

FIG. 6 is an elevation of the showing in FIG. 5;

FIG. 7 is a section, on an enlarged scale, taken generally on line VII—VII in FIG. 2;

FIG. 8 is a section taken on line VIII—VIII in FIG. 2;

FIG. 9 is an enlarged fragmentary portion of FIG. 2;

FIG. 10 is a section, on an enlarged scale, taken on line X—X in FIG. 2;

40 FIG. 11 is a section, on an enlarged scale, taken on line XI—XI in FIG. 2;

FIG. 12 is a plan view of an alternate pair of draw bars especially adapted for forming packages from polyethylene film;

45 FIG. 13 is a section taken generally on line XIII—XIII in FIG. 12;

FIG. 14 is a section, on an enlarged scale, taken on line XIV—XIV in FIG. 12 and showing the draw bars in a gripping position;

50 FIG. 15 is a section taken generally on line XV—XV in FIG. 12;

FIG. 16 is a fragmentary section similar to FIG. 14 showing the draw bars in a sealing position;

55 FIG. 17 is a view, on an enlarged scale, showing an electrical connection to one of the draw bars in FIG. 12;

FIG. 18 is a front elevation of the volumetric feeder of the present invention;

FIG. 19 is a side elevation of this feeder;

60 FIG. 20 is a section taken on line XX—XX in FIG. 18;

FIG. 21 is a section taken on line XXI—XXI in FIG. 18;

FIG. 22 is a rear elevation of one end of the means employed for mounting a supply roll of wrapper material and showing the braking means therefor;

65 FIG. 23 is a side elevation of the showing in FIG. 22;

FIG. 24 is a fragmentary view, partly in section, showing connections to a web take-off roll;

70 FIG. 25 is a view showing a web brake and taken as a section transverse the web brake elements;

FIG. 26 is a section taken on line XXVI—XXVI in FIG. 25;

FIG. 27 is a section through a web control roll showing the mounting means therefor;

FIG. 28 is a section taken on line XXVIII—XXVIII in FIG. 27;

FIG. 29 is a front elevation, with portions broken away, of the mounting means for the wrapper tube forming means;

FIG. 30 is an end elevation of these mounting means;

FIG. 31 is a fragmentary plan view of a positioning device for these mounting means;

FIG. 32 is a plan view of mechanism for longitudinally seaming a wrapper tube of polyethylene film;

FIG. 33 is a section, on an enlarged scale, taken generally on line XXXIII—XXXIII in FIG. 32;

FIG. 34 is a section, on a further enlarged scale, taken on line XXXIV—XXXIV in FIG. 33;

FIG. 35 is a section, also on a further enlarged scale, taken on line XXXV—XXXV in FIG. 33;

FIG. 36 is a schematic view of the water circuit;

FIG. 37 is a schematic view of the air circuit;

FIG. 38 is a schematic view of the electrical connections for the draw bars;

FIG. 39 is a schematic view showing certain cam controlled switches for the electrical circuit; and

FIG. 40 is a simplified diagrammatic showing of the electrical circuit for the machine.

The overall organization of the present packaging machine may best be had by referring to FIG. 1 in the drawings. There it will be seen that a pair of supply rolls 30 of heat-sealable wrapper material are mounted at the rear of the machine. A web W is led from one or both of the rolls 30, around a pair of fixed idler rolls 32, 34, over a web take-off roll 36 and then down and around a fixed idler roll 38. For the sake of clarity, only one web is described herein. From the roll 38 the web W extends upwardly past electric eye mechanism 40 and web braking means 42 to a fixed idler roll 44. From this point the web passes around an angle control roll 46 to an outside former or folder 48 which is designed to guide the web so that as it is advanced it will assume a tubular form as it is wrapped around a tubular inside former 50, with the side edges of the wrapper lapped in a vertical seam at the front of the machine.

In the illustrated position, the tube T of wrapper material extends below the lower end of the former 50 and is sealed off at its lower end by a previously formed transverse heat-sealed seam. A pair of draw bars 52, 54 are shown in readiness to move toward the tube T, grip the tube, move downwardly and form a second transverse seam to complete a pillow-shaped package for the charge of product seen in the lower end of the tube.

The draw bars are slidably mounted on a swinging arm 56 which is pivotally connected to the frame of the machine by links 58, 60. An air motor 62 is mounted on the arm 56 and through linkage means (not shown in FIG. 1) is adapted to open and close the draw bars 52, 54 against the tube T.

As illustrated, the next step is for the air motor 62 to close the draw bars 52, 54. Thereafter, or at approximately the same time, the draw bars will move downwardly along a substantially straight line vertical path. This straight movement is attained by the described links 58, 60 and by a link 64 connected at one end to the arm 56 and at its other end to a revolving crank arm 66.

As the draw bars 52, 54 move down, the tube is severed, by means carried therewith, intermediate the transverse heat-seal. As the draw bars near the bottom of their stroke the air motor 62 is actuated by the electric eye mechanism 40; there being electric eye actuating indicia spaced along the web W a distance equalling package length. The draw bars 52, 54 are opened by motor 62, releasing the tube T and the package which was completed by severing the tube on the downstroke. The completed package falls into a chute 67 leading to a collection point at the front of the machine.

After or during the opening of the draw bars 52, 54, the arm 56 swings upwardly to return the draw bars to their upper position, as illustrated.

During the upstroke of the draw bars, the web W is clamped by the braking means 42 as the take-off roll 36 moves upwardly to draw off a length of web W from the supply rolls 30. In this connection it will be seen that the roll 36 is connected to the arm 56 by links 68 and urged upwardly by springs 70.

While the tube T is stationary during the upstroke of the draw bars, a heat-sealer 72 is swung towards the former 50 to heat-seal the vertical seam of the tube.

Product is introduced into the tube T during the interval of time between closure of the draw bars in their upper position and return of the draw bars to their open position again in their upper position. Product is fed from a columetric feeder 74 which drops a given volume of product into the upper end of the former 50. Although other types of feeders can be employed, the feeder 74 is particularly adapted to meeting the high speeds of operation of the present machine.

The above brief outline will serve as an aid to a ready understanding of the detailed description which follows. In most instances ball bearings and bearing sleeves have been omitted for the sake of simplicity, as will be apparent to those skilled in the art.

Swinging Arm Mechanism and Package Length Adjustments

Reference is now made to FIGS. 2 and 3. The arm 56 is an assembly comprising a cast bracket or platform 76 and a pair of parallel rods 78 projecting forwardly therefrom to provide unobstructed cantilevers. The draw bars 52, 54 are slidably mounted on the rods 78.

The mounting links 58 for the arm 56 are respectively received by bifurcated ears 80 on opposite sides of the platform 76. Pins 82 pivotally connect the platform 76 to the inner ends of the links 58 while pins 84 pivotally connect the outer ends of these links to frame members 86. The links 68, extending to the take-off roll 36 are also pivotally mounted on the pins 82.

At the rear of the platform 76 are two projections 88 having a shaft 90 journaled therein and axially positioned by collars 92. The lower ends of links 60 are pivotally mounted on the outer ends of shaft 90 and held in place by collars 94. The upper ends of the links 60 are pivotally connected to the frame members 86 by pins 96. Collars 98 retain the links 60 on the pins 96.

It was previously noted that the crank link 64 is pivotally connected to the arm 56. Actually the point of this pivotal connection is adjustable for purposes which later appear. Thus it will be seen that a lever 100 is pivotally mounted on the shaft 90 and projects therefrom beneath the platform 76. The lever 100 has a slotted arm 102 through which a clamping screw 104 passes and is threaded into a lug 105 on the upper surface of the platform 76 to secure the lever 100 in fixed relation thereto. The upper end of link 64 is connected to the lever 100 by a shoulder screw 106. An adjusting screw 108 is threaded through the platform 76 and bears against the lever 100 to assist in maintaining the desired angular relation between these two members. Also the screw 108 may be employed to obtain an accurate adjustment of the platform 76 relative to the link 64.

Referring now to FIGS. 4 and 5, it will be seen that the lower end of the link 64 is connected to the crank arm 66 by a pin 110. The crank arm is in fact an adjustable throw crank arm of two-piece construction. In the sense of being a two-piece construction, there is a crank plate 112 (see also FIG. 6) welded to a crank shaft 114 and a T-slotted arm 116 which is loosely mounted at its inner end on a reduced diameter 115 formed on the outer end of the shaft 114. The shaft 114 does not project into the T-slot of the arm 116 so as not to obstruct the slot. A single screw 118 passes through the crank plate

112 and is threaded into the arm 116. This provides a safety feature in the event of an obstruction to the free movement of the swinging arm 56; the screw 118 will shear before any of the more complicated and harder to replace parts can be broken. Once the obstruction has been cleared, a sheared screw can be replaced and normal operation of the machine resumed.

As for the adjustability of the crank arm 66, it will be seen that the pin 110 projects from a slide block 120 confined within the T-slot of the arm 116 with a nut 121 holding the link 64 thereon. The block 120 is movable toward and away from the shaft 114 upon rotation of a screw 122 which passes through a plate 124 secured to the outer end of the arm 116 and is threaded through the block 120. A collar 126 prevents axial movement of the screw 122 relative to the plate 124 and arm 116. Thus the screw 124 may be rotated to vary the effective throw of the crank arm 66.

The shaft 114 is journalled on a pair of pillow blocks 128 and has a sprocket 130 secured to its other end. A chain 131 connects the sprocket 130 to the output shaft of a variable speed drive 132 seen only in FIG. 1. The variable speed drive comprises also the motor M which is actuated by the electrical circuit later described.

With the swinging arm mounted on the links 58 and 60, as described, rotation of the crank arm 66 will result in to and fro movement being imparted to the draw bars 52, 54. When the draw bars are clamped against the tube T in their closed position, they will be constrained to a substantially straight path as they move down and draw the tube from the former 50. The path of movement of the draw bars is illustrated by the phantom showing in FIG. 3, wherein it will be seen that the draw bars tilt slightly about a horizontal median line, intersecting the axis of the former 50, as they move downwardly. This substantially straight motion has been found effective and the slight tilting action of no consequence is drawing off the wrapper tube.

The length of the package is a function of the downward movement of the draw bars which in turn is dependent on the throw of the crank arm 66. When the packages have printed matter, there is a registration problem. It is then that the electric eye 40 is employed to actuate opening movement of the draw bars in response to indicia on the web W which are spaced apart in accordance with package length. With the electric eye in use the throw of the crank 66 is adjusted so that the downward stroke of the draw bars will be slightly greater than the package length. Where there is no registration problem, the draw bars are opened at the bottom of the down-stroke, by means later described, so that package length is a direct function of the throw of the crank 66.

Adjustment of the throw of crank 66 is made by rotating the screw 122 (FIG. 5). The relationship of crank throw to package length is calibrated and indicated by indicia 136 on the arm 116 (FIG. 6). An index finger 132, secured to the slide block 120, extends through a slot 134 in the arm 116 and may be matched against the indicia 136 to quickly obtain the needed stroke of the draw bars for a given bag length.

It will be appreciated that as the throw of the crank 66 is varied, the upper limit of the stroke of the draw bars will also be varied. It is desirable that the draw bars start each stroke or cycle a given distance from the bottom of the inside former 50. It is for this reason that the swinging arm 56 is adjustable relative to the point of pivotal connection with the link 64. Thus, after the crank 66 has been adjusted for the desired throw and with the link 64 in its highest position, the screw 104 will be loosened and the screw 108 turned to raise or lower the platform 76 relative to the lever 100 and bring the draw bars 52 to their desired height. In the drawings the crank 66 is adjusted for maximum throw. Any adjustment would shorten this throw which in turn means

that the draw bars would need to be raised in adjusting the screw 108.

With a shorter stroke it is then possible to attain higher production rates, without undue stresses, by increasing the speed of rotation of the crank 66. A hand wheel 138 is provided at the front of the machine (FIG. 1) for varying the output speed of the variable drive 132 and in turn the rate of rotation of the crank 66.

10 The variable speed drive 132 and its means of adjustment comprises a conventional variable pitch cone pulley construction and need not be described in any further detail.

15 It will be pointed out at this time that a minimum of power is required to reciprocate the draw bars by reason of the fact that counterbalancing means are provided for the weight of the arm 56 and draw bars 52, 54. These means comprise the tension springs 70 (FIG. 1) which are connected at the upper ends of the links 68. The springs 70 are in turn connected at their upper ends to the 20 frame of the machine. The springs 139 tend to lift the arm 56 and draw bars 52, 54 and balance their weight. Thus a minimum of power is required to move the draw bars up and down. The use of spring counterbalancing means is preferred because of the minimum additional 25 mass involved.

Draw Bars and Means for Opening and Closing the Draw Bars

Reference is first made to FIGS. 2 and 3 for a description 30 of the constructional features of the draw bars 52, 54.

The draw bars 52, 54 are both slidably mounted on the rods 78. Circular bushings are provided at one end of each draw bar and an oval bushing, indicated in FIG. 8, is provided at the other end of each draw bar. The oval bushings compensate for lengthwise expansion of the draw bars when they are heated during operation of the machine and assure free sliding movement of the draw bars on the rods 78.

40 A pair of vertically spaced, elongated, heated grippers 142 are mounted on the draw bar 52 by way of a resilient mounting bar 144. The grippers 142 are heated by resistance heaters 147 (FIGS. 2 and 7) encased within the mounting bar 144 with an electrical lead 145 extending to a junction box 149 secured to the draw bar 52 (FIG. 3). The grippers 142 are secured to the bar 142 by screws 146. Screws 148 (FIGS. 2 and 8) are threaded into the mounting bar 144 on its horizontal centerline and slidably pass through the draw bar 52. Nuts 150 are threaded onto the outer ends of the screws 148 and limit movement of the gripper 142 away from the draw bars 52. A pair of screws 152 are threaded into the draw bar 52 adjacent and equi-spaced above and below each of the screws 148. The screws are provided with check nuts 154 and each has an enlarged head which bears against a spring 156 and the grippers 142 are yielding urged away from the draw bar 52 as limited by the screws 148. In normal operation the springs 156 will be compressed each time the draw bars are closed 55 which means that in each operation the screws 148 will slide relative to the draw bar 52. A circular bushing is provided for one screw 148 and an oval bushing for the other of these screws so as to insure free sliding action when the mounting bar is heated and expands relative to the draw bar 52.

60 A pair of vertically spaced, elongated, heated grippers 158 (FIGS. 2 and 7) are secured in relatively fixed relation to the rear draw bar 54 and in opposed relation to the grippers 142 on the front draw bar 52. Thus it will be seen that the grippers 158 are secured to a mounting bar 160 by screws 162. Resistance heaters 164 encased within the mounting bar 160 supply heat to the grippers 158 with an electrical wire 165 (FIG. 3) extending from the heaters 164 to a junction box 167 mounted on the draw bar 54. Screws 166 (FIGS. 2 and 7) pass through

the draw bar 54 and are threaded into the mounting bar 160 generally on its horizontal centerline. A pair of screws 168 are threaded through the draw bar 54 and bear against the mounting bar 160 adjacent to and above and below each screw 166 to rigidly hold the mounting bar and grippers 158 in a position determined by the screws 166. The screws 168, it will be seen, control the angular relation of the mounting bar 160 and grippers 158 relative to the draw bar 54. These screws are adjusted so that when the swing arm 56 is in its horizontal position the outer heat-sealing face of the grippers will lie in a vertical plane normal to the axes of the rods 78.

Guards 170 (FIG. 7) are secured to the upper surfaces of the mounting bars 144 and 160 by screws 172. When the draw bars are closed and product is dropped into the tube T, there is a possibility that the tube will contact the heated mounting bars or grippers above the area thereof which is to be heat-sealed. It is this danger and resultant damage to the packages which is prevented by the guards 170.

On the lower faces of the mounting bars 144, 160, plates 174 (FIG. 7) are secured by screws 176. Sponge rubber blocks 178 are mounted in opposed relation on the plates 174. As the draw bars close, the rubber blocks 178 compress the tube T and expel excess air therefrom before it is sealed off to form a finished package.

Strippers 180 in the form of angle plates are also mounted on each draw bar. A rod 182 is secured to each stripper and passes through a journal in each mounting bar (144 or 160) and then through a journal in the draw bar (52 or 54). A spring 184 urges each stripper 180 outwardly of the heated grippers (142 or 158). Nuts 186 are threaded onto the other end of each rod and in combination with a load bearing collar 188, limit this outward movement of the strippers. After the tube T has been heat-sealed and as the draw bars are opened, the strippers 180 will promptly free the tube should there be any tendency for it to stick to the heated grippers 142 or 158.

The draw bars are moved toward and away from each other by linkage mechanism which is powered by the air motor 62 (FIG. 2). The air motor is mounted on the platform 76 of the swinging arm 56 by means of a collar 192 telescoped over the cylinder of the air motor 62. Pintles project from opposite sides of the collar 192 and are pivotably received by blocks 190 secured to the platform 76 by screws 191.

The piston rod 194 (FIGS. 2 and 10) of the air motor 62 is threaded into a connector 196 disposed between the plates of a bifurcated lever 198 and connected thereto by a pin 200. A flanged bumper member 202 is keyed to the shaft 90 and secured to the lever 198 by a screw 204 threaded into one of a series of three holes 206 so that the lever 198 is relatively fixed or fast on the shaft 90. It will be apparent that with this structure the shaft 90 will be oscillated when the air motor 62 is actuated to reciprocate the piston rod 194.

The bumper member 202 has one pressure pad 208 on which a hard rubber bumper 210 is mounted, and a second pressure pad 212 underlying the lever 198, and also having a hard rubber bumper 214 mounted thereon. It will next be noted that a channel member 216 extends between the platform projections 88 (FIGS. 2 and 3) and is secured thereto by screws 218. Hard rubber bumpers 220, 222 are mounted on the channel member 216 to be engaged by the bumpers 210, 214 respectively when the air motor 62 is actuated.

At each end of the shaft 90 there is a double-ended toggle lever 224 (FIGS. 2 and 11) which is keyed to the shaft 90 and held in place thereon by binding screws 226. A connector 228 is pivotally mounted on one bifurcated end of each lever 224 by a pin 230. A tube 232 is brazed to each connector 228. The tubes 232 extend to the front draw bar 52 (see also FIG. 3) where they are joined to similar connectors 234 which enter slots 236 formed in

each end of the draw bar 52. Pins 238 pivotally link the connectors 234 to the draw bar 52 and are held in place by set screws 240. A connector 242 is pivotally mounted within the other bifurcated end of each lever 224 on a pin 244. A tube 246 is brazed at one end to each connector 242; at the other end to a connector 248. The connectors 248 enter slots 250 formed in each end of the rear draw bar 54. Pins 252 pivotally connect the connectors 248 to the draw bar 54 and are held in place thereon by set screws 254.

The air motor 62 is double acting and is alternately actuated to oscillate the shaft 90 and the double-ended levers 224 90° (relative to platform 76) between the full line and phantom showings in FIG. 11. In the phantom position of the levers, the tubes 232 are displaced forwardly thereby shifting the front drawing bar 52 outwardly on the rods 78 while the tubes 246 are simultaneously displaced rearwardly thereby retracting the rear draw bar 54 along the rods 78 bringing the draw bars to their open position shown in phantom in FIG. 3. The draw bars 52, 54 are opened by simultaneous movement of each and conversely are closed simultaneously by a reverse stroke of the piston rod 194 and returned to their illustrated gripping position.

It will be seen that the levers 224 provide a toggle effect in clamping the draw bars against the tube T. The leverage advantage obtained thereby substantially reduces the amount of air power required to press the tube T together in forming an effective heat-seal. It will be noted that the amount of sliding movement of the front draw bar 52 on rods 78 is somewhat greater than that of the rear draw bar 54. This is desirable because of the angular relation between the swing arm 56 and the tube of wrapper material T. In this fashion the length of stroke necessary for the piston rod 194 is minimized.

The illustrated relation of the various parts for opening and closing the draw bars 52, 54 is adapted to accommodate the maximum size or diameter tube of wrapper material for which the present machine is designed. However, as will be brought forth hereinafter, an alternate former 50 may be employed where it is desired to produce smaller packages from a tube of lesser diameter. For efficient operation it is then desirable to reduce the distance between the draw bars 52, 54 in their open position and thus the amount of travel of each. This adjustment is readily made by shifting the lever 198 relative to the flange member 202 (FIG. 10). To do so, the screw 204 is removed and then threaded into one of the other threaded holes 206. The phantom showing of the piston rod connector 196 illustrates this adjustment made for a minimum diameter tube. When so adjusted the shaft 90 will be rotated a lesser angular extent as indicated by the phantom position of the bumper 210. The draw bars will then be opened a corresponding lesser amount.

This means for controlling flow of air to the motor 62 and timing its operation to the vertical movement of the draw bars 52, 54 will be described in detail hereinafter.

One of the important advantages of the present invention is the ease with which the various machine components may be serviced and replaced, and particularly the draw bars 52, 54. The front draw bar 52 is removed by loosening the set screws 240 and removing the pins 238. In this fashion the only mechanical connection to the front draw bar 52 is broken. The electrical wires supplying current for the heaters 147 are connected to a junction box by a quick disconnect coupling which is readily released as is more fully described hereinafter. The front draw bar is then free to be slid off the ends of the anti-lever rods 78 for repair or to be replaced by a different type of draw bar such as the alternate form of draw bar described hereinafter. Similarly, in the case of the rear draw bar 54, the only linkage connection can be removed simply by loosening the set screws 254 and removing the pins 252 to free the draw bar from the tube connectors 248. Again a quick disconnect electrical coupling is

provided for the wires providing current for the resistance heaters 164. Also there are air connections hereinafter described mounted on the draw bar 54 which are also the quick disconnect type so that no particular training or skill is required in removing the draw bar 54. The rear draw bar may also be quickly slid off the unobstructed ends of the cantilever rods 78.

Package Severing and Perforating Mechanism

A knife 258 (FIGS. 2, 7 and 9) for severing finished packages is disposed within a slot 260 running lengthwise between the heated grippers 158 on the rear draw bar 54. The knife 258 is mounted on a U-shaped frame comprising rods 262 to which the ends of the knife 258 are pinned. The rods 262 have threaded reduced diameters at their other ends which pass through holes in a transverse bar 264 and are clamped thereon by nuts 266. The bar 264 is suitably apertured to provide clearance and access for the screws 166 and 162. An air motor 268 projects into a horizontal slot formed in the draw bar 54 and is secured thereon by screws 270. The piston rod 272 of this air motor is threaded into the bar 264 on its midpoint.

The tube T is gripped and heat-sealed by the grippers 142, 158 when the draw bars are closed. When the air motor 270 is actuated, the knife 258 will be projected through the tube T, clamped between the grippers 158 and 142, and into a slot 274 (FIG. 7) in the mounting bar 144. The tube is thus severed intermediate the length that has been heat-sealed and a completed package is formed, which package will be released when the draw bars open.

There are occasions where it is desirable to string several packages together with the individual packages being readily separable. For such purposes means are provided for perforating the tube rather than severing it. In this connection it will be noted that the knife 258 has an interrupted or serrated edge of sawtooth form. Means are provided for limiting the extent of travel of the knife so that these sawteeth will puncture the tube without completely severing it. These means comprise an air motor 276 (FIG. 7) secured by screws 278 to a plate 280 which is in turn secured by screws 282 to the rear face of the draw bar 54. A plate 284 is secured to the piston rod 286 of motor 276. The plate 286 is angled downwardly and has a depending lip which is disposed to limit forward movement of the bar 264 when the piston rod is lowered. This obstructive relation is illustrated in FIG. 9 where the knife 258 is shown in its perforating position relative to the tube T. When the plate 286 is in this obstructive position and the knife 258 projected toward the tube T under the yieldable force of the air motor 268, the points of its teeth will pierce the tube T forming perforations which define the upper end of a finished package.

Means, hereinafter described, are provided for cycling the air supply to the motor 276 so that any desired number of packages can be defined by perforation and then the plate 286 raised or maintained out of obstructive relation whereupon a given group of packages will be severed from the tube as the knife 258 completes its full forward stroke. Alternatively the plate 286 can be maintained in the illustrated elevated position so that a completed package will be severed during each cycle of operation of the machine.

Alternate Draw Bars for Polyethylene or Like Wrapper Materials

Reference is next made to FIGS. 12 and 13 showing alternate draw bars 288, 290 slidably mounted on the rods 78. These draw bars are connected to the tubular links 232, 246 and are moved on the rods 78 toward and away from each other to grip the tube T in the same fashion as the draw bars 52, 54, above described. Likewise, they are moved up and down in the same fashion as previously described for the draw bars 52, 54.

Associated with the front draw bar 288 is a plate 292

which has two studs 294 that are received by holes in the draw bar 288 and adjustably positioned thereon by nuts 296. A central pressure plate 298, preferably formed of insulation material, is secured to the plate 292 by screws 300. Projecting from the top and bottom of the plate 292 are a pair of fixed guides 302. A pair of U-shaped brackets 304 are secured to the rear of plate 292 by screws 306 (FIG. 13) which are threaded into the guides 302. A gripper 308 (FIG. 14) is disposed between each guide plate 302 and the central pressure plate 298. The grippers 308 are surfaced with sandpaper in order to obtain a good grip on the wrapper tube. Bearing plates 310 are provided to insure free sliding movement of the grippers 308. Pins 312 pass through holes in the guides 302, bearings 310 and pressure plate 298. Further, the pins 312 pass through slots (FIG. 14) in the grippers 308 to provide for limited sliding movement of the grippers relative to the pressure plate 298. Springs 314 yieldingly urge the grippers 308 outwardly with an adjustable force. Thus it will be seen that the springs 314 (FIGS. 12 and 14) are seated in recesses formed in the rear faces of the grippers 308, pass through the plate 292 and are seated on screws 316 threaded through the brackets 304.

The central pressure plate 292 has a groove running the length of its outer face which receives a square rubber rod 318 (FIGS. 2 and 14). A pressure or cut-off wire 320 runs the length of the rubber rod 318. A mounting pad 322 is secured to one end of the pressure plate 298 by a screw 324. The wire 320 has a bead at one end so that the wire may be placed in a slot formed in the pad 322 with the bead caught on the illustrated undercut portion thereof (FIG. 12). A mounting pad 328 is pivotally connected to the other end of the pressure plate 298 by a pin 330. The wire 320 is confined in a slot in the pad 328 and has a bead at its other end which is caught on the illustrated undercut portion of the pad 328. A spring 334 urges the pad 328 outwardly from the end of the plate 298 and maintains the wire 320 taut at all times.

Preferably electrical connections are made with the mounting pads 322, 328 by way of insulated wires 329, 331. The wires 329, 331 are connected in an electrical circuit, as later explained, for heating the cut-off wire to a slightly elevated temperature in the order of 100°-150° F.

For purposes which later appear, a rod 336 is mounted at each of the four corners of the plate 292. The rods 336 project towards the rear draw bar 290 and are held in place by nuts 338.

Referring now to the rear draw bar 290, it will first be noted that a rectangular plate 340 (FIGS. 12 and 15) is confined at its ends within horizontally disposed slots formed in the rear draw bar and held in place thereon by screws 342.

A cooling plate or water tank 344 (FIGS. 12, 14 and 15) is horizontally and centrally disposed at the front of the draw bar 290. A pair of springs 346 urge the water tank outwardly of the plate 340. A pair of rods 348 are pinned to the tank 344 and project rearwardly through slots in the ends of the plate 340. A spacing collar 350 is telescoped over the projecting ends of each rod 348 so that nuts 352 threaded onto the ends of the rods may be readily accessible. It will be apparent that the outer position of the water tank 344 is established by

adjustment of the nuts 352 on the rods 348 and that the water tank may yield rearwardly against the springs 346. The water tank 344 is formed with a passageway 354 (FIG. 12) from one end to the other and opening on the rear face thereof. A pair of rearwardly projecting pipes 356 are inserted into the ends of the passageways 354 and pass through the slots in the ends of the plate 340. One of these pipes is connected through a flexible conduit to a source of cooling water while the other of said pipes is connected to a drain again by means of a flexible conduit, later explained in greater detail.

A pair of guides 358 (FIGS. 12, 13 and 14) are rigidly mounted on the draw bar 290 in opposed relation to the guides 302 on the front draw bar 288. This end is attained by screws 360 which pass through the draw bar 290, spacing collars 362, and bars 364 and are threaded into each end of each guide 358. Screws 366 pass through each guide 358 and are threaded into grippers 368 which are thus non-yieldingly mounted in opposed relation to the yieldingly mounted grippers 308. The grippers 368 are also surfaced with sand paper for better gripping power. It will be noted that spacer plates 370 are inserted between each adjacent guide 358 and gripper 368.

A stripper 372 (FIGS. 13 and 14) is disposed between each of the grippers 368 and the water tank 344. The strippers are in the form of sheet metal angle plates which are secured by their vertically disposed portions to bars 374. The bars 374 are slotted (see phantom showing in FIG. 15) at each end and slidably ride on the spacing collars 362. Springs 376 are coiled around the collars 362 and bear against the bars 374 to urge the strippers 372 outwardly so that when the draw bars are open they project beyond the water tank 344, as indicated in FIG. 13. Pads 378 (FIG. 15) are provided on the strippers to span the slotted ends of the bars 374. From FIG. 13 it will be seen that prior to final closing movement of the draw bars, the rods 336 will engage the pads 378 and displace the strippers to a retracted position behind the front face of the water tank 344 as seen in FIG. 14.

A mounting block 380 of insulating material is secured to one end of the water tank 344 by a screw 382. A flat electrical resistance wire 384 (FIG. 17) has an eye secured at one end thereof which is fastened to the block 380 by a screw 386. An electrical connection is made with this end of the resistance wire 384 through a wire 388 which is also secured to the block 380 by the screw 386. The wire 386 extends to a junction box 389 on the lower adjacent side of the draw bar 290 (FIG. 15). A second mounting block 390 (FIG. 12) of insulating material is pivotally mounted on the other end of the water tank by means of a pin 392. An eye is secured to the other end of the resistance wire 384 which in turn is fastened to the block 390 by a screw 394 and an electrical connection is made with this end of resistance wire 384 by a wire 396 which is also secured to the block 390 by the screw 394 in the same fashion as shown in FIG. 17. The wire 396 extends to a junction box 397 (FIG. 15) mounted on the undersurface of the adjacent end of the draw bar 390. A spring 398 (FIG. 12) urges the block 390 outwardly and maintains the resistance wire 384 taut at all times.

A sheet 400 (FIG. 14) of woven fiber glass cloth extends from the rear of the draw bar 290 and is disposed between the water tank 344 and the resistance wire 384 to insulate the wire from the tank. A second sheet 402 of woven fiber glass extends from the rear of the draw bar 290 and overlies the wire 384. The sheet 402 prevents the tube T from sticking to the wire 384 when the latter is heated to heat-seal the tube. Preferably both impregnated with polytetrafluoroethylene.

The portions of the sheets 400, 402 underlying and overlying the resistance wire 384 become charred or worn in use and require replacement. It is with this in mind that both ends of each of these sheets are threaded through a slot 404 (FIG. 13) formed in the draw bar 290. A bar 406 spans the water tubes 356 and is positioned thereon by collars 408. Clamping plates 409 are provided to clamp the sheets 400, 402 against the upper and lower surfaces of the bar 406 and are held in clamping relation by wing nuts 410 threaded onto screws 412 which are held fast in the central bar 406. The various clamping surfaces may be surfaced with sandpaper to increase their gripping power. When it is desired to shift the sheets 400, 402 it is a simple matter to loosen the nuts 410 and pull one end or the other of these sheets to bring a fresh working surface to the resistance wire 384. A supply

roll may be provided for the sheets 400, 402 or a goodly length thereof may be simply suspended in the fashion illustrated.

The operation of the draw bars 288, 290 will now be given. The preferred timing of the operation is for the draw bars to close and grip the tube Tp when raised to their highest position. The tube Tp is formed of polyethylene or like wrapper material. Having gripped the tube Tp, the draw bars 288, 290 start to move downwardly. In the act of gripping the tube, the grippers 308 and 368 will first clamp the tube Tp at points spaced above and below the water tank 344. In so doing the tube Tp between these clamped points will be constrained to an angular or tortuous path as it bends over the projecting water tank 344 and more particularly the resistance wire 384 thereacross. This condition is illustrated in FIG. 14 where the grippers 308 are shown yieldingly clamping the tube Tp against the relatively rigid grippers 368. Now as the draw bars 288, 290 are further moved towards one another to their fully closed position, the water tank 344 will yield against the springs 346 (FIG. 12) as the grippers 308 yield further relative to the front draw bar 288. As this occurs, the portion of the tube Tp between the vertically spaced pairs of grippers 308, 368 will be deflected towards a less tortuous path (FIG. 16). The area of the tube which is to be heat-sealed thus is brought to a substantially limp condition free of any stresses.

At this point, note will be taken of the fact that when a charge of product is suspended in the tube Tp considerable stress will exist in the polyethylene material. It has been found that by relieving the stresses in the tube Tp by the means described, that a much more effective and reliable heat-seal can be made in the tube.

The means for making the heat-seal comprises the resistance wire 384 which is heated by a pulse of current when the draw bars are fully closed. The wire 320 presses against the opposite side of the tube Tp and severs it when the wire 384 is heated. Simultaneously two transverse heat-sealed seams are formed in the tube, one closing off the top of a finished package and the other closing off the bottom of the next package to be formed. It has been found that by heating the wire 320 as above described, effective heat-seals may be made at a much faster rate, particularly where the ambient temperature is relatively low. This is true even though it is necessary to substantially cool the heat-sealed portions before they can be released by the pressure wire 320 and pressure block 318.

The use of an impulse of current for performing a heat-sealing operation is not novel, per se. For this reason no detailed description will be given of the electrical circuit therefor, though later mention will be made as to how its actuation fits into the overall mode of operation of the present machine.

Reverting to the operation of the draw bars 288, 290 when they are opened to release the tube Tp and the package severed therefrom, the strippers 372 move forwardly to insure a positive separation of the tube and package from the draw bars so that the draw bars will be free to move upwardly and repeat the cycle just described.

Product Feed

FIGS. 18, 19, 20 and 21, show the volumetric feed device 74 in detail. The volumetric feed device herein disclosed is the subject of a separate co-pending divisional application. This device comprises a group of rotating cups 412 arranged in radially aligned pairs which are filled with product from a hopper 414. The cups are each provided with a pivotally mounted bottom closure 416 which opens to allow the product to drop therefrom as each successive pair of cups is rotated above a funnel 418 leading to the inside former 50. The cups 412 each comprise a lower cylindrical shell 420 into which an upper cylindrical shell 422 is telescoped.

The lower set of shells are mounted on a spoked plate 424 (FIG. 20), each spoke of which has a pair of cup receiving sockets aligned radially of a vertical shaft 426. A clamp 428 holds a pair of cup shells 420 in each set of aligned sockets, with a screw 430 threaded through a projection on each adjacent spoke to releasably maintain the clamp 428 in place. The bottom closures 416 (FIGS. 18 and 19) are mounted in pairs on the plate 424 in cooperative relation with the lower ends of the shells 420. More specifically a pair of studs 432 depend from the plate 424 and carry a mounting bar 434 for the closures. Needle bearings on the bar 434 provide a pivotal mounting for plates 436 to which the bottom closures 416 are attached. A leaf spring 438 is secured to the lower face of each plate 436.

When a pair of cups 412 are over the funnel 418, the bottom closures 416 hang freely to allow product to drop into the inside former. Upon further rotation of the cups 412, the closures 416 will be cammed upwardly as the leaf springs engage rods 440. The rods 440 are secured to a platform 444 which is supported by brackets 446, 448. It will be seen that as the cups 412 rotate over the platform 444, the closures 416 are maintained in sealing relation to the bottoms thereof by the deflected leaf springs 438.

The upper shells 422 (FIGS. 18 and 21) are also arranged in pairs aligned radially of the shaft 426. Each pair of shells 422 is received by holes in an upper plate 450, with the upper end faces of the shells 422 flush with the top surface of the plate. A groove is formed in each shell 422 immediately beneath the top plate 450. A wedge-shaped plate 452 is forced into the grooves of adjacent pairs of shells 422 by a screw 454 which passes through a flange 456, welded to the plate 452, and is threaded into the top plate 450. A shoulder screw 458 is threaded into a blind hole tapped in the plate 450 centrally of each wedge-shaped plate 452. The shoulder screws pass through keyhole slots formed in the plates 452 to allow the plates to be retracted for removal or replacement of the shells 422.

The lower spoked plate 424 is secured by screws 466 to a flanged collar 462 which in turn is keyed to the shaft 426 by a key 463 (FIG. 20) and held fast thereon by set screws 464 (FIGS. 18 and 19). The top plate 450 is secured to an elongated hub 466 by screws 468. The hub 466 is telescoped over the upper end of the shaft 426 and is provided with a keyway for receiving the elongated key 463. The shaft 426 and the hub 466 thus rotate together with the upper end of the hub 466 being journaled on and suspended from a top cross bar 469 by means of the illustrated ball bearing 471. A bevel gear 470 is pinned to the shaft 426 adjacent its lower end and has a hub which bears against the inner race of a ball bearing 472. The bearing 472 is mounted on a bracket 474 which in turn is secured to a main support plate 476 by screws 478. The support plate 476 spans frame members 480 and is secured thereto by screws 482. It will be noted that the brackets 446 and 448 are also secured to the support plate 476.

Reverting back to the bearing 472 (FIG. 18), this bearing is designed to take the axial thrust of all elements secured to the shaft 426. The ball bearing 471 in the top cross bar 469 is designed to take the axial thrust of all parts secured to the hub 466. An additional journal for the lower end portion of the shaft 426 is provided in the bracket 474.

A bevel gear 484 is secured to one end of a cross shaft 486 and meshes with the gear 470. A guard 487 protects the gears 470, 484. The shaft 486 is journaled in the bracket 446. An angularly adjustable (for timing purposes) sprocket 490 is secured to the opposite end of the cross shaft 486. A chain 492 (FIGS. 1 and 19) extends from the sprocket 490 to a single tooth clutch 494. A chain 496 connects the output shaft of the variable speed

drive 132 with the clutch 494 to provide power for rotating the cups 412.

An actuating rod 498 (FIG. 1) extends from the clutch 494 to the front of the machine. A knob 500 is mounted on the outer end of the rod 498 which may be readily grasped to engage and disengage the clutch 494. Thus it is possible, by disengaging the clutch 494, to operate the machine without feeding product to the inside former as when making repairs or feeding a new web of wrapper material. When the clutch 494 is engaged, its single tooth characteristic will insure proper timing of the feeding of product once such timing has already been established.

The hopper 414 from which product is fed to the cups 412 is per se of conventional construction. The hopper comprises front wall 502 and a sloping rear wall 504 (FIGS. 19 and 21) adjustably spaced above the top plate 450. The hopper itself is mounted on a frame 506 which in turn is secured to the cross bar 469 by screws 510. It can be seen that product poured into the hopper 414 will flow onto the plate 450 and into the cups 412. Inner and outer guides 512 and 514 control the width of spread of the product on the rotating top plate 450. A doctor blade 516 engages the top plate 450 and spans the guides 512, 514. The doctor blade 516 is mounted on a plate 518 to which the front ends of the guides 512, 514 are also secured. The plate 518 is in turn secured to the top cross bar 596 by a strap 519. Thus the rotating cups 412 will first be filled with product as they pass beneath the hopper 414 and then the product will be leveled at the top of each cup as they pass beneath the doctor blade 516 thereby giving an accurate volumetric measure of product.

After a given pair of cups passes by the doctor blade 516 they will come to an opening in the plate 444 defined by the edges 520 (FIG. 20), whereupon the bottom closures 416 will fall away (FIG. 18) dumping the product into the inside former 50.

It is often necessary to adjust the volume of the cups 412 in order to obtain an accurate correlation between weight and volume for a given product. Such adjustment is made by varying the extent to which the upper and lower shells 422, 420 are telescoped. This procedure, of necessity, involves trial and error until the correct relation is established. In order that a minimum of time be required in establishing the desired volume of the cups 412, provision is made for varying the volume of the cups as the machine is operating and product is being packaged.

In this connection attention is next directed to vertical posts 530 (FIG. 18) which are threadably received by nuts 532 secured to the undersurface of cross bar 496 at opposite ends thereof. The posts 530 each are provided with a collar 533 which rotates on a thrust washer 534 supported by the bracket 446 or 448. A worm gear 536 is secured to each post 530. The brackets 446 and 448 are each provided with extensions for journaling a cross shaft 538 (FIG. 19). Adjacent each end of the shaft 538, a worm 540 is secured thereto and meshes with one of the worm gears 536. A sprocket 542 is secured to one end of the shaft 538 and a chain 544 extends to a lower sprocket 546 (FIG. 1) which is connected through appropriate gearing to a hand wheel 547. The hand wheel 547 is conveniently disposed at the front of the machine for rotation by an operator to obtain the desired volume of the cups 412.

Thus when the hand wheel 546 is rotated, the posts 530 are rotated simultaneously to raise or lower the top cross bar 496. The top plate 450 and the hopper 501 are both supported from the cross bar 496 and move therewith as the upper shells 422 are moved to vary the extent to which they are telescoped in the lower shells 420. In this fashion the volume of the cups 412 is varied as the machine is operating. By weighing packages and adjusting cup volume, the desired package weight can be arrived at in a very minimum of time.

It will be appreciated that the cups do not necessarily

have to be arranged in pairs. This and other modifications will be apparent to those skilled in the art.

*Web Supply Roll Mounting Means and Control Brake
Therefor*

The mounting means for the two supply rolls 30, seen in FIG. 1, is identical for each and therefore only one such means will be described in detail, with reference being made to FIGS. 22 and 23. The supply roll 30 is mounted, by means of flanges 556, on a shaft 550 which is rotatably mounted by an upwardly open journal at each end. Each of these journals comprises a pair of ball bearings 552 (only the right hand pair is shown) mounted on a bracket 554. The brackets 554 are provided with sloping surfaces 555 on which the shaft 550 may be placed and then rolled onto the bearings 552.

The illustrated bracket 554 is secured to a vertical frame member 558 by screws 560. A pin 562 is secured to the bracket 554 and an arm 564 is pivotally mounted thereon. A second arm 564 is mounted in similar fashion at the opposite side of the machine and a slackener roll 565 is mounted on the lower end of these arms. A roller 566 is mounted on the side of arm 564 and rides on a curved bar 568. The curved bar 568 is secured, by screws 570, to an arm 572 which is pivotally mounted on a pin 574. The pin 574 projects from a block 576 which is secured to a plate 578 by screws 580 and the plate 578 is in turn secured to the vertical frame member 558 by screws 582. A brake 584 is secured to the arm 572 and disposed to engage a drum 586 which is keyed to the supply roll shaft 550.

When there is a pull on the web W drawn from the roll 30, the slackener roll will be raised and with it the arms 564 as they swing about the pin 562 (see the phantom position in FIG. 23). As this occurs the arm 572 will be swung in a direction which carries the brake 584 away from braking engagement with the drum 586. This results from the fact that the surface of the bar 568, engaged by roll 566, is slightly eccentric relative to the pin 562. With this eccentric relation, it is possible to obtain a very delicate and accurate control of the braking force applied to the drum 586. In this fashion the rate of rotation of the supply roll is closely controlled so that no excess will be drawn therefrom nor will the pull required to advance the web be excessive (a problem which is of particular pertinence where the web is intermittently advanced, as in the present machine).

While the weight of the lever 572 and the parts secured thereto could be sufficient to provide the necessary maximum braking force, it has been found advantageous to provide the illustrated spring 587 to obtain the proper braking force and tension control for the web. The spring 587, it will be noted, is connected at one end to the arm 572 and at its other end (not shown) to the frame of the machine. The arms 564 and slackener roll 34 are urged by springs 588 to a lower position which is limited by engagement of the arms 564 with a fixed cross bar 590 or a lower position defined by the amount of web which may be drawn before full braking force stops rotation of the roll 30.

With this arrangement there is at all times a controlled loop of the web W about the slackener roll 565. This loop is formed as the web passes from the supply roll 30 to an idler roll 591, around the slackener roll 565 and then to the idler roll 32 (FIG. 1). When the web W is advanced with a maximum acceleration, this loop is at its shortest extent, little or no braking force is applied to the drum 588 and the supply roll rotates freely. When the web begins to decelerate, the loop around roll 34 will increase and a progressively increasing brake force will be applied to the drum 588, thereby slowing down the rate of rotation of the supply roll 30 so that it will not overrun.

Provision is also made for axially shifting the roll 30 so that proper tracking of the web W may be obtained

as it is drawn through the machine. To this end a flange 592 is secured to the shaft 550. A grooved collar 594 receives the flange 592 and is secured to a screw 596 which is threaded, at one end, into the bracket 554. A split bearing 598 is formed on the bracket 554 to receive the other end of the screw 596. A knurled nut 600 is secured to the outer end of the screw 596 so that it may be conveniently rotated to obtain the desired axial position of the roll 30. A screw 602 may then be tightened to clamp the split bearing 598 and lock the screw 596 in this adjusted position.

Web Guiding and Tube Forming Means

From the slackener roll 565 (FIG. 1) the web W passes over idler rolls 32, 34 and then around the take-off roll 36. As was earlier noted, the take-off roll 36 is connected to the swinging arm 56 by links 68 with the springs 70 urging the roll 36 upwardly. Referring now to FIG. 24, the connection between the links 68 and take-off roll 36 is illustrated in greater detail by the view of one end of that roll. The roll 36 is rotatably mounted on a shaft 604 to the opposite ends of which the links 68 are fastened by set screws 606. The lower ends of the tension springs 70 are hooked into grooves formed between the roll 36 and the links 68. The upper end of each spring 70 is hooked into a screw eye 608 secured to a frame member at the top of the machine.

The web brake 42, previously referred to, comprises (FIGS. 25 and 26) a fixed rubber roll 610 having a shaft 612 which is received by brackets 614 on the side frame members 86. Set screws 616 normally prevent rotation of the roll 610 but permit adjustment so that a new surface thereof can be positioned in operating relation to the web W. A second rubber roll 618 is mounted in opposed relation to the roll 610 and has a shaft 619 which is received by arms 620. Set screws 622 normally prevent rotation of the roll 618 relative to the arms 622. The arms 622 are secured to a cross shaft 624 which is journaled at each end on a bearing 626 secured to the adjacent side frame of the machine. An actuating lever 628 is also secured to the shaft 624 and projects above the piston rod 630 of an air motor 632 secured to the adjacent side frame member 86. A tension spring 634, extending between the lever 628 and the adjacent side frame member, normally maintains the roll 618 inoperative and out of braking engagement with the web W.

When the draw bars 52, 54 are opened to release the wrapper tube, it is then the preferred time to actuate the web brake 42. Actuating means, hereinafter described, at this time direct air to the air motor or cylinder 632. The piston rod 630 of the air motor 632 underlies the lever 628. When the air motor 632 is actuated, the piston rod 630 causes the shaft 624 to rotate and forcibly clamps the web W between the rolls 612, 618.

At the time the web W is clamped, or shortly thereafter, the swinging arm 56 and the draw bars 52, 54 (FIG. 1) will begin their upstroke. As this occurs, the take-off roll 36 will also move upwardly drawing a further length of web from the supply roll 30 and storing it in a controlled loop. When the draw bars again clamp the wrapper material tube T to begin their downstroke, the air motor 632 will automatically be de-energized and the web brake 40 rendered inoperative. As the draw bars 52, 54 move downwardly, the length of web looped around the take-off roll 36 is payed off and drawn to the tube former 50. It will be noted that the arm 56 swings relative to the links 60, even though the draw bars 52, 54 are moving in a substantially straight line path. With this in mind, it will be seen that the links 68 are advantageously connected to the arm 56 at a point approximately half the distance from the connection to the links 60, to the draw bars 52, 54. This means that the movement of the roll 36 is approximately half that of the draw bars. Since the web is doubled over the roll 36 in a parallel or completely reversed loop, upward movement of that roll will draw a

length of web approximating the length of web used in forming a package. Preferably it is arranged that the length of web drawn by the take-off roll is slightly less than the package length. This means that as the draw bars move down, the portion of the web advanced toward the former 50 is mostly supplied from the loop around the take-off roll and just a small length is fed from the supply roll 30 at this time. With this arrangement and the supply roll brake, just described, the web W is maintained taut at all times. A further advantage is that a minimum of power is required in drawing the web from the supply roll during the downstroke of the draw bars, and yet there will be no excess of web drawn from the supply roll.

It will also be appreciated that the power requirements for the machine are further minimized by the effect of the counterbalancing springs 70.

In passing it will be noted that the electric eye device (FIG. 1) comprises a conventional photoelectric cell adjustable along the length of the web and arranged to be actuated by indicia provided at regularly spaced intervals on the web.

From the brake mechanism 42, the web W passes over the idler roll 44 and then around the positioning roll 46 which controls the angle of the web as it approaches the outside former 48. The roll 46 (FIGS. 27 and 28) is rotatably mounted on a shaft 635 which has a block 636 secured to each end (only the right hand end is shown). The blocks 636 are slidably mounted on brackets 638 secured to opposite frame panels 86 by screws 640. A screw 642 is threaded through each block 636 and is journaled on lugs 644 projecting through the brackets 638. Collars 646 prevent axial movement of the screws 642 relative to the brackets 638. Knobs 648 are secured to the outer ends of the screws 642 and indicia plates 649 are secured to the brackets 638 for ready reference to the adjustment of each end of the shaft 636.

The configuration of the folding faces of the folder 48 are of known design and need not be described in detail. It will be noted that the outside folder 48 has a concentric spaced relation with the inside tube former 50 which must be closely controlled. One of the advantages of the present construction is that once this relation is established for a given former and folder, it will at all times be maintained even when remounted on the machine after different size former and folders have been in use. This and the constructional features in mounting the folder 48 and former 50 are separately claimed in a divisional application, Serial No. 55,577, filed September 12, 1960.

It will be seen (FIGS. 29 and 30) that arms 650 project from the winged portions of the folder 48 and are clamped against the lower ends of threaded posts 652 by nuts 654. The posts 652 are suspended from a plate 656 and are held thereon by nuts 658. The inside former 50 is provided with a flange 660 at its upper end which is secured to the plate 656 by screws 662. It will also be noted that the funnel 418 is provided with a flange 664 which is secured to the plate 656 by screws 666. The wrapper tube formers and folder are thus mounted as a unit in fixed relation to each other on the plate 656. The plate 656 is, of course, apertured so that product will pass from the funnel 418 to the inside former 50.

The plate 656 is detachably mounted in fixed relation on the frame of the machine. It will be seen that the plate 656 spans and rests on the upper frame member 480. A square locating lug 668 is secured to each of the frame members 480 by a nut 670. Each end of the plate 656 is slotted at 672 to be interdigitated or telescoped over the locating lugs 668. Screws 674 project into the front, rear and inner sides of the slots 672 (FIG. 31). In making an original setup, the plate 656 is placed on the frame members 480 and the screws 674 adjusted to obtain the proper transverse and longitudinal location of the inside and outside formers (50 and 48) in the machine. Once this desired location is established, the screws 674

are locked in place by check nuts 676. The plate 656 is then clamped against the frame members 480 by screws 678 which pass through large clearance holes or slots in the plate 656.

- 5 Different size inside and outside formers are mounted in the same fashion on plates identical with the plate 656. Thus, to change to a different size package, it is simply necessary to remove the screws 678 and lift the plate 656 from the machine, and with it the folder inside former. An alternate plate having different size inside and outside formers may then be set on the frame members. The new inside and outside formers will automatically be correctly positioned by the locating lugs 668, presuming the locating screws 674 of the new plate have previously been properly adjusted. It will be noted that the screws 674 do not grip the lugs 668 but engage them with a sliding fit to permit ready replacement of the plate 656.

The alternate former units preferably have the different size folders mounted so that a constant or fixed height-wise location of the outside formers is obtained. This is obtained by using the same height posts 652 for each unit. It will also be appreciated that different size formers are themselves of different heights. As was previously stated, 20 it is desirable that the web W have a given angular relation as it approaches the outside former 48. Once a new size outside former is mounted in the machine, it is a simple matter to adjust the roll 46 by means of the knobs 648 in order to obtain this desired angular relation.

- 25 30 The web W is wrapped into tubular form, about the former 50, and lapped to form a vertical seam. This seam is then heat-sealed to complete the tube T of wrapper material which is drawn from the former 50 by the draw bars 52, 54. The means for heat-sealing this vertical seam, when using cellophane or the like, follow the principles of operation previously known for this purpose and therefore will only be briefly described with reference to FIG. 1.

35 40 The vertical heat-sealing element 72 (FIG. 1) is mounted on a frame 682 in opposed relation to the vertical seam in the wrapper material surrounding the former 50. The frame 682 is mounted by means of a hinge to one side of the machine frame. A rod 686 is hooked over a pin at the other side of the frame 682. The rod 686 is 45 connected to one arm of a bell crank 688. The other end of the bell crank 688 is connected to a link 690 which extends to the lower portion of the machine where it is connected to a three-armed pivotally mounted lever 692. A spring 694 is connected to another arm of the lever 50 50 55 60 65 692 and urges a cam roll on the third arm thereof against a cam 696. The cam 696 is secured to the shaft 114 which rotates once for each machine cycle, as previously explained.

When the draw bars are being raised, the wrapper 55 material is held against movement relative to the inside former 50. It is at this time that the frame 682 will be swung to bring the resistance heated sealer 72 into heat-sealing engagement with the wrapper material seam. The duration of engagement is predetermined to obtain a 60 proper heat-seal. The heat-sealing pressure is yieldingly applied by reason of the spring connection between the rod 686 and the bell crank 688.

Where the wrapper material is polyethylene or the like, it has been found preferable to replace the resistance heat-sealer 72 with an impulse heat-sealing unit 697, just as the draw bars 52, 54 are preferably replaced by the draw bars 288, 290.

- 65 70 75 Referring now to FIGS. 32-35, it will be seen that the pivoted frame 682 carries the impulse resistance sealing unit 697, which unit comprises a mounting member or water tank 698, secured to a plate 700 by screws 702. A stud 704 projects from the plate 700 and passes through a hole in the frame 682 with a nut 706 threaded onto the outer end thereof. A pair of screws 708 are threaded through the frame 682 and bear against the plate 700.

above and below the stud 704. The screws 708 are adjusted to align the resistance heater unit in a vertical plane with the inside former 50 while the nut 706 is adjusted to correctly position the heater unit 697 longitudinally of the machine in accordance with the diameter of the former 50.

An impulse resistance ribbon 709 is connected to a strip 711 which is secured by screw 710 to an insulating mounting pad 712. Another strip 711 is connected to the other end of the ribbon 709 which in turn is secured to a second insulating mounting pad 714 by screw 716. The pad 712 is secured to the lower end of the water tank 698 by screws 718. The pad 714 is pivotally mounted on a pin 720 which extends between projections from the upper end of the tank 698. Spring 722 bears against pad 714 and maintains the ribbon 709 taut. A sheet 724 (shown only in FIG. 35) of insulation, preferably fiber glass cloth impregnated with polytetrafluoroethylene, is interposed between the ribbon 709 and the tank 698. A second sheet 725 of such material overlies the ribbon 709. A pair of bars 726 clamp the ends of the sheets 724 so that they may be kept taut. Each bar 726 is telescoped over a pair of studs 727 which are brazed onto upper and lower tang-like extensions of the tank 698. Wing nuts 728 hold the bars 726 in clamping relation.

At the upper end of the ribbon 709 an electrical connection is made by a wire 730 which is secured to block 714 by the screw 716. The wire 730 is led downward of the neat-sealing element through an internal passageway formed by recesses in the tank 698 and plate 700 (FIGS. 34 and 35). An electrical connection is made with the lower end of the ribbon 709 by a wire 732 which is connected to the block 712 by the screw 710. The wires 730, 732 are joined in a cable leading to a quick disconnect connector 734 mounted on the frame 682. A cable 736 extends from the connector 734 along a recess in the frame 682 to the hinge side thereof. From here the cable may pass to a fixed support point on the frame and then to electrical circuitry yet to be described.

At this point it will also be noted that the cable 736 carries the wires for the resistance heat-sealing element 72 which may be plugged into the connector 634 when the element 72 replaces the impulse heat-sealing unit now being described. The connector 634 is polarized so that the different heat-sealing elements are automatically connected to different electrical circuits.

Cooling water is supplied to the tank 698 by a hose 738 which is connected to a tube 740 at one end of a passageway 742 through the tank 698. A tube 744 projects from the other end of this passageway and is connected to a discharge hose 746. Preferably the hoses 738 and 746 are connected to the tubes 740 and 744 by quick disconnect couplings 748 to facilitate interchangeability of the two heat-sealing units.

The hoses 738 and 746 are led through a recess in the frame 682 to the hinge side thereof. From this point on they may extend to a fixed point on the frame and then to a water source and drain respectively.

The ease of interchanging the resistance sealer 72 and impulse sealer 697 will be readily apparent. The frame 682 can be swung clear of the machine and the electrical and mechanical connections made or broken by the couplings 734 and 748, while the only mechanical connection involves manipulation of the knob 706.

Air, Water and Electrical Control Circuits

Water is employed only when the impulse draw bars 288, 290 and long seam sealer 697 (FIGS. 12-16) are used. The water circuit is provided solely for cooling the impulse heater elements thereof and is extremely simple. The circuit for the long seam sealer 697 is believed to have been sufficiently described in connection with FIGS. 32-35 and no further details thereof will be given.

A pipe 750 (shown only in FIG. 36) is connected at one end to a block 751, and at the other end to a source

of cooling water. The block 751 is mounted on the frame member 86 of the machine and a flexible hose 752 carries the water from the pipe 750 to a block 754 mounted to the rear and adjacent side of the platform channel iron 216. The water passes through a passageway in the block 754 and a tube 756 to a quick disconnect coupling 758 at the front of the channel iron 216. The coupling 758 connects a flexible hose 760 to the swing arm 56. The hose 760 extends to the movable draw bar 290 and is connected to one of the water tubes 356 projecting from the water tank 344 (see also FIG. 12). From the water tank the water flows back through a flexible hose 761 which is secured to the other tube 356. A quick disconnect coupling 762 connects the hose 761 to the draw bar 56, being mounted on the channel iron 216. Next, the water flows through a pipe 764 to the block 754 and a passageway therein to a flexible hose 766. The hose 766 returns the water from the block 754 to the fixed block 751 and a drain pipe 768.

A valve 769 is interposed in the drain pipe 750 so that the flow of water can be controlled at the proper rate or shut off if the impulse type heater is not being used. Also, the quick disconnect couplings 758 and 762 are preferably self-sealing in order to facilitate removal of the rear draw bar 290.

Dealing next with the air circuit (FIG. 37) it will first be noted that two of the air motors previously referred to are always employed regardless of whether the draw bars 52, 54 or 288, 290 are in use. These are the air motor 632 for operating the web brake and the air motor 62 for opening and closing the draw bars.

The air motor 632 is connected to a spring returned three-way solenoid valve 770 (shown only in FIG. 37) by way of a pipe 772. The valve 770 is mounted on the frame of the machine adjacent the air motor and is connected to a source of pressurized air by a pipe 774. The source of pressure air may be provided by a compressor on the machine or may be supplied from a factory air supply. When the solenoid valve 770 is energized, as later explained, the piston rod of the air motor 632 will be extended and the wrapper web clamped by the brake 42. When the valve 770 is de-energized, the air motor is vented to atmosphere and the brake 42 is released by the spring 634 (see also FIG. 25).

The air motor 62 is mounted on the swinging arm platform 76 and is powered in the following manner. A pipe or header 776 (shown only in FIG. 33) is mounted on the frame of the machine adjacent the swinging arm 56 and is connected to the source of pressurized air. A flexible hose 778 extends from the header 776 to a distributing block 780 mounted on the platform 76. A hose 782 extends from the block 780 to a solenoid controlled four-way valve 784. Flexible hoses 786, 788 connect opposite ends of the air motor 62 to the valve 784. When the valve 784 is energized, air is alternately fed to opposite ends of the air motor 62. The piston rod 194 thereof is extended and retracted by power strokes in each direction to open and close the draw bars 52, 54.

When the resistance draw bars 52, 54 are employed, it is also necessary to provide air connections for operating the cut-off knife 258. It will be seen that a hose 790 extends from the distributing block 780 to a spring returned four-way solenoid valve 791 mounted on the channel iron 216. A pair of flexible hoses 792, 794 connect the valve 791 with opposite ends of the air motor 268 and make a connection between the arm 56 and the draw bar 54. It will be seen that quick disconnect couplings 795 are provided at the ends of the hoses 792, 794 to enable quick removal of the draw bar 54. When the valve 791 is energized, the knife 258 is projected forwardly to sever the tube of wrapper material. When the valve 791 is de-energized, the knife is retracted by an alternate power stroke of the air motor 268.

The perforating means, while highly desirable for certain applications, is an optional feature. When em-

ployed, a hose 796 extends from the block 780 to a spring returned, solenoid controlled four-way valve 798 mounted on the channel iron 216. A pair of flexible hoses 800, 802 connect opposite ends of the air motor 276 to the valve 798 and make a connection between the arm 56 and the draw bar 54. Quick disconnect couplings 803 are provided at the ends of the hoses 792, 794, again for the purpose of enabling easy removal of the draw bar 54. When the valve 798 is energized, the air motor 276 is actuated to limit movement of the knife 258 to a perforating operation, as previously explained.

All of the solenoid valves 770, 784, 791 and 798 are of conventional design and are preferably of the pilot valve type. The valves 770, 791 and 798 have a spring biased pilot valve so that only one coil is required for their operation. The actuation of these valves is controlled by switches in the electrical circuit which is next to be described.

The electrical connections to the swinging arm 56 are diagrammatically illustrated in FIG. 38. A junction box 804 is mounted on the frame member 86 adjacent the swinging arm 56 and all electrical connections to the swinging arm are made from this point. There are three quick disconnect contact units provided in the junction box 804.

Discussing first the connections used for the resistance-type draw bars 52, 54, a quick disconnect connector 806 is plugged into the first contact unit of the junction box 804. A flexible cable 808 extends to the junction box 167 mounted on the undersurface of the adjacent end of the rear draw bar 54. From here leads 167 extend to the heater elements 164 on the rear draw bar. A quick disconnect connector 810 connects a flexible cable 812 to the junction box 149 on the front draw bar 52. Leads 145 extend from the junction box 149 and provide electrical energy to the resistance heaters 147.

A second connector 816 is plugged into the junction box 804 and connects a flexible cable 818 to a junction box 820 mounted on the undersurface of the arm bracket 76. A cable 822 extends from the junction box 820 to the solenoid valve 784 and carries signals thereto from the cable 818. A third connector 824 is plugged into the junction box 804 and connects a second flexible cable 826 to the junction box 820 and carries the energizing signals for actuating the knife valve 791 and perforating control valve 798. A cable 828 extends from the junction box 820 to the valves 791 and 798 and carries the signals therefor.

When it is desired to remove the draw bars 52, 54 the procedure is very simple. The connector 810 is unplugged from the junction box 814 and the pins 238 (FIG. 2) removed. The draw bar 52 may now be readily slid off the free ends of the rods 78. Next the connector 806 is unplugged from the junction box 804, the air hose connectors 795 and 803 (FIG. 37) are broken and the pins 252 are removed. The rear draw bar 54 may then be slid off the ends of the rods 78.

Installing and removing the impulse draw bars 288, 290 is likewise a simple procedure. The rear draw bar 290 is first slid onto the rods 78. The links 246 are connected thereto by the pins 252 (FIG. 12). A flexible cable 832 (FIG. 34) extending from the junction box 389 is connected to the junction box 804 by plugging a connector 834 into the first contact unit from which the connector 806 has been removed. Current for the impulse heater wire 384 passes through the cable 832 and then the lead 386. The lead 396 connected to the other end of the impulse wire 384 extends to the junction box 397 and the circuit therefor is completed through a cable 836 extending between the junction boxes 397 and 389. At this point it will be noted that the first contact unit of the junction box has its contacts arranged so that the connector 834 is electrically connected to one circuit while the connector 806 is electrically connected to a different circuit. The two circuits are arranged to prop-

erly energize the heater elements being used. The connectors 806 and 836 are polarized so that each may be plugged into the junction box 804 in only the desired or operative position.

5 Next the front draw bar 288 is slid onto the rods 78 and connected to the links 232 by the pins 238. A connector frame 838 is plugged into a junction box 839 on the frame 86 to provide current for heating the cut-off wire 320. The connector 838 is at the end of a flexible cable 840 extending from a junction box 842 mounted on the undersurface of draw bar 288. The lead 329 for wire 320 extends to the junction box, while the lead 331 extends to a junction box 844 with a wire 846 completing the heating circuit back to junction box 842 and cable 840.

10 Having hooked up the electrical connection for the draw bar 288, 290, the water line connectors 758, 762 (FIG. 36) are next made to establish the cooling water circuit. The valve 769 may then be opened to permit controlled water flow. The impulse draw bars are now 15 ready for operation.

20 The electrical circuit for the present machine includes several cam controlled switches. The mechanical mounting of these switches will now be explained as a preliminary to describing the electrical circuit. These switches 25 may be mounted at any convenient location and in the present machine are disposed at the upper left-hand corner.

25 Referring to FIG. 39, a suitably journaled cam shaft 30 849 is driven, by chains and sprockets not shown, from the variable speed drive 132 so that the shaft 848 rotates once each machine cycle.

30 Two spiral barrel cams 852, 854 and six plate cams 35 858, 860, 864, 866, 868 and 870 are secured to the shaft 848 and may be angularly adjusted thereon to obtain proper timed relation of the switches actuated thereby relative to the cycle of machine operation. Such adjustment is, however, only required in the initial setup operation. No attempt has been made to show the actual cam 40 constructions as they could be worked out by one skilled in the art. The relative positions of the working surfaces of these cams will be apparent in the following description of operation.

35 Switches 872 and 874 are secured respectively to plates 45 876, 877 and have roller levers engaging the cams 852, 854 for actuation thereby. The plate 876 is mounted on rods 878 and 880. The rods 878 threadably engages the plate 876 while the rod 880 provides a sliding bearing therefor. The rod 880 threadably engages the plate 50 877 while the rod 878 provides a sliding bearing therefor.

Knobs 882, 883 are secured to the rods 878, 880 respectively and are accessible at the front of the machine for rotation by an operator. It will be apparent that the 55 knobs 882, 883 may be rotated to individually adjust the axial position of the switches 872, 874 relative to the cams 852, 854 respectively. This adjustment is for timing purposes as will be more fully developed hereinafter.

60 Switches 886, 888, 892, 894, 896 and 898 are respectively arranged to be actuated by the cams 858, 860, 864, 866, 868 and 870. Each of these last-named switches is mounted on a plate 900 which has an integral hub 902 telescoped over a fixed shaft 904. A set screw 906 in each 65 hub holds each switch in engagement with its respective cam. If, for a given operation, one of these last-named switches is not required, it may be swung to an inoperative position merely by loosening its set screw 906.

70 The electrical circuit for the machine is schematically 75 illustrated in FIG. 40. For the sake of clarity, fuses, overload relays and machine jogging circuitry and other conventional elements have been omitted.

The main drive motor M, for the variable speed drive 75 132, is connected to a source of three-phase alternating

current by the lines 920, 922 and 924. Relay contacts R-1-1, R-1-2 and R-1-3 are interposed in these lines to control the starting and stopping of this motor. At this point, it will be noted, with one exception, all relay contacts are shown twice, once in the circuits where they are electrically connected and again in association with the relay in its actuating circuit. The wires 920, 922 are connected to opposite sides of the primary of a transformer T. The secondary of the transformer 927 is connected at one end to wire 926 and at the other end to wire 928. Various circuits are connected across the wires 926, 928.

The start-stop circuit comprises a normally closed stop switch 930, a start switch 932, and the coil of relay R-1. Hold-in contacts R-1-4 are arranged in parallel around the start switch 932. The machine is started by closing switch 932 to energize relay R-1 thereby starting the motor M as the contacts R-1-1, -2 and -3 close. Switch 932 is then released as hold-in contacts R-1-4 keep the circuit energized. The machine is, of course, stopped by opening switch 930.

The next circuit controls heat for the resistance sealing units and comprises an off-on switch 936 placed in series with a relay R-2. When the switch 936 is closed, relay contacts R-2-1 are closed to complete the circuit to the vertical seam heat-sealer 72. This is seen in the separate circuit across the lines 920, 922 wherein the heater element 72 is in series with the contact R-2-1 when it is plugged into the connector 734. Also the contacts R-2-2 close to complete another circuit across the lines 920, 922 which supplies current for the resistance heaters 147, 164. The contact unit 806 is, of course, plugged into the junction box 904 at this time.

The next circuit controls clamping and unclamping movement of the draw bars 52, 54 or 288, 290. An on-off switch 938 permits this circuit to be selectively energized. The solenoid control valve 784 for air motor 62 comprises two coils 784a and 784b. Cam controlled switch 872 is connected in series with coil 784a and relay contacts R-3-1 are connected in series with coil 784b, cam controlled switch 874 is connected in parallel across the contacts R-3-1.

Also controlled by the switch 938 is the circuit for actuating the web brake 42. This circuit includes the coil of solenoid valve 770 and relay contacts R-3-2 arranged in series, with the cam controlled switch 886 connected in parallel across the contacts R-3-2.

The next circuit is for the electric eye used in obtaining registration of printed matter on the wrapper material. An off-on switch 940 is provided so that this circuit can also be selectively energized. The electric eye circuit 942, including its thyratron tube, is connected across the lines 926, 928. The coil of a pilot relay R-4 is arranged to be energized when the electric eye circuit is energized by an indicia on the wrapper web. The contacts of relay R-4 are connected in series with the coil of a working relay R-3 across the lines 926, 928. De-energization of the electric eye circuit is obtained by opening the cam controlled switch 888.

Also controlled by the on-off switch 938 are the circuits for actuating the cut-off knife and perforating means. A disconnect coupling 939 is provided so that these circuits may be completely de-energized when using the impulse draw bars 288, 290. The circuit for actuating the cut-off knife comprises the cam controlled switch 892 connected in series with the coil of the solenoid valve 791. The perforator circuit comprises an on-off switch 961, an electronic counter 962 connected in series with the cam controlled switch 894. A further circuit is provided through the counter in series with the cam controlled switch 896 and the coil of solenoid valve 798. The switches 894, 896 are closed each machine cycle. The switch 896 closes to actuate the valve 798 on each cycle. The switch 894 actuates the counter so that after a given number of machine cycles the branch circuit, to the coil of valve 798, will remain open when

the switch 896 is closed. Thus, each time the valve 798 is actuated, the tube of wrapper material will be perforated, and each machine cycle in which the valve 798 is not actuated the tube will be severed. The counter 962 is adjustable so that the number of packages strung together may be controlled at will.

When the impulse draw bars 288, 290 are used, the last two circuits are employed and the control circuitry for the cut-off knife and perforating means are dispensed with. The next circuit thus comprises control means for the long seam impulse sealer 697. This circuit includes an on-off switch 941 connected in series with an electronic timer 943. The timer is actuated by a triggering circuit 945 which is connected in series with the cam controlled switch 898 which is connected to the line 928 through the off-on switch 938. With this arrangement, the draw bars must be in operation before the impulse circuit for the long seam sealer 697 to be energized. From the timer 943, a branch circuit passes through the coil of a relay R-5. The contacts R-5-1 thereof are connected in series with the resistance ribbon 709 when the long seam sealer is plugged into the connector unit 734. In operation, with the switches 938, 941 closed, the switch 892 will be closed each machine cycle and, in response to such closure, the triggering circuit will actuate the timer. The relay R-5 will then be momentarily closed for a controlled length of time, which results in a pulse of current flowing through the ribbon 709. Although not shown in the present diagram, it is necessary that there be provided transformer means, of known design, for obtaining a sufficiently large pulse of current to produce the necessary heat in the ribbon 709 for sealing purposes.

The next circuit controls current for the draw bars 288, 290 and comprises an off-on switch 944 connected in series with an electronic timer 946. From line 928 a microswitch 954 is connected in series with a triggering circuit 949 for the timer 946. From the timer 946 there is a branch circuit through the coil of relay R-6.

The microswitch 954 is physically mounted on the channel 216 (FIG. 11) of the swinging arm 56 and is arranged to be closed when the double-ended lever 224 is in the illustrated full line position wherein the draw bars 288, 290 will be fully closed (FIG. 16). This being the time in the machine cycle when it is desired to actuate the heat-sealing means.

Thus with the switch 944 closed, microswitch 954 will close when the draw bars are closed, thereby actuating the triggering circuit which will cause the timer 946 to energize the coil of the relay R-6 for a controlled momentary period. The contacts R-6-1 are connected in series with the ribbon 384 on the rear draw bar 390 when the contact unit 834 is plugged into the junction box 804. Again in accordance with known design, transformer means would be provided, though not shown, to obtain the necessary current for producing sufficient heat for heat-sealing process.

A further branch circuit is controlled by the off-on switch 944 and comprises a variable resistor 960 placed in series with the cut-off wire 320 when it is plugged into the contact unit 838. By adjusting the resistor 960, it is possible to obtain the desired heat on the cut-off wire 320.

Operation

Operation of the machine with the resistance draw bars 52, 54 will first be described. The draw bars are mounted in the fashion indicated in FIGS. 1-11, 37 and 38. As a preliminary step, the switches (FIG. 40) 936, 938 and 940 are first closed. Presuming a web of paper has already been threaded through the machine and that the clutch 494 has been engaged for the volumetric feed, the machine is now ready for operation, which may be commenced by closing the main start switch 932.

At this time it will be assumed that the draw bars 52, 54 are at their upper limit of travel and have just been closed, by the air motor 62 (FIG. 3), to grip and clamp

the tube T of wrapper material. At this moment the web brake 42 is released and the longitudinal heat-sealer 72 is swung clear of the tube former 50. The draw bars are now moved downwardly by the rotating crank 66 and maintained in a straight line path by the described linkage arrangement including the links 58, 60. It will be noted that the draw bars are clamped against the tube T above a charge of product previously deposited therein. As soon as the draw bars are closed, the volumetric feeder 74 will release a successive charge of product which will fall through the inside former 50 into the tube T.

As the draw bars move downwardly the web W is fed onto the former 50 from the loop around the take-off roll 36, as that roll moves downwardly.

During downward movement of the draw bars, the tube T is sealed along transverse seams by the vertically spaced, opposed heat-sealers 142, 158 (FIG. 7). Shortly after (though the timing is not too critical) the draw bars are clamped against the tube T the knife 258 (FIGS. 7-9) is actuated to sever the tube T intermediate this heat-sealed area. Such actuation is provided by cam 864 (FIG. 39) which closes switch 892 (FIG. 40) which in turn results in the air motor projecting the knife 258 forward to sever the tube T.

Where the perforator control is employed, cam 866 (FIG. 39) will, prior to this time, close switch 894 (FIG. 40) to actuate the counter 962. Also prior to actuation of the knife 258, the switch 896 is closed by cam 868. Dependent upon the setting and cycling of the counter 962, the valve 798 will either be energized or remain de-energized for this given cycle. If de-energized, the knife 258 will sever the tube. If the valve 798 is energized, the air motor 276 (FIGS. 7-9) moves the plate 284 downwardly bringing it into effective obstructive relation relative to the knife 258 as it is interposed between the bar 264 and the mounting block 160. The knife is thus limited to a forward position of movement in which its serrated edge perforates the tube T without actually severing it (FIG. 9).

While retraction of the knife 258 is not too critical it is preferable that the solenoid valve 791 be de-energized shortly after the knife has severed or perforated the web, this results in the knife automatically being retracted. The same is true of the valve 798 which is de-energized at about the same time so that the plate 284 is automatically raised.

As the draw bars 52, 54 approach the bottom of the downstroke the indicia mark provided on the web W will come to the electric eye 40 (FIG. 1) causing the electric eye circuit 942 (FIG. 36) to fire and the relay R-3 to be energized.

Closure of relay contacts 9-3-1 results in energization of the solenoid coil 784b which actuates the air motor 62 (FIGS. 1 and 36) to move the draw bars 52, 54 to their open position as the tube T is unclamped and a finished package released. Simultaneously the contacts R-3-2 also close to energize solenoid valve 770 and cause the brake 42 to grip the web W.

The vertical stroke of the draw bars is somewhat longer than the desired package length. In the event of a failure in the electric eye circuit, e.g. a missing indicium on the web W, alternate means, comprising the switches 874 and 886, are provided for actuating the opening of the draw bars and also actuating the web brake 42. These means would also be employed where there was no web registration problem. Thus it is arranged so that the switches 874, 886 open at the bottom of the downstroke of the draw bars. This insures that the wrapper tube will be released before the draw bars begin their upstroke and also clear the product fill tube during their upstroke. Also it is insured that the web W is clamped so that the weight of the product in the tube will not pull the web out of register.

At this point it will be noted that the air motor 62

requires a relatively large volume of air for its operation due to stroke and power needs for opening and closing the draw bars. This results in a rather substantial inertia or lag time between the time when the valve 784 is actuated and the time movement of the draw bars actually begins. Where as in the present machine the operating speed is a variable, this lag time presents a particular problem. In opening the draw bars, this problem is overcome by the mounting for switch 874 which permits it to be adjusted relative to the spiral cam 854 while the machine is operating. It is thus possible to time the actuation of switch 874 so that the draw bars will open and release the wrapper tube just at the bottom of their downstroke for a given machine speed. When the speed of the machine is changed, this timed relation may be readily re-established by changing the position of the switch 874 relative to cam 852.

While there is some lag time in the actuation of the air motor 632 for the web brake 42, it has been found to be so short that it can be disregarded. This is by reason of the fact that the air motor 632 is relatively small and has a short stroke. Thus the actuating switch 886 therefor is controlled by the simple plate cam 858.

With these described means, when the draw bars reach the bottom of their downstroke, the wrapper tube will be released and the web brake will be applied. As soon as the draw bars are fully open (this occurs before any substantial upward movement) the switch 888 (FIG. 40) opens de-energizing relays R-3 and R-4. Relay contacts R-3-1 open and at about the same time switch 874 opens de-energizing coil 784b. The draw bars will not close again, however, until coil 784a is energized. Contacts R-3-2 also open, but valve 770 is maintained energized by switch 886 and the web brake 42 continues to grip the web.

Thus, during the upstroke of the draw bars the wrapper tube is held stationary as a further length of web is drawn from the supply roll 30 by the take-off roll 36.

When the draw bars approach the top of their upstroke, switch 872 is closed to energize solenoid coil 784a and actuate the air motor 62 to close the draw bars and clamp the wrapper tube. In closing the draw bars, there is not only the inertia or lag time, already mentioned, but also a delay time between the time when the draw bars start to close and when they effectively grip the wrapper tube. Therefore, the switch 872 is adjustable relative to the spiral cam 852 so that its time of actuation may also be varied as the machine is operating to cause the draw bars to grip the wrapper tube just at the top of their upstroke. At this time, i.e., the top of the stroke, the switch 886 will open allowing the web brake 42 to release the web so that the downstroke may begin.

Shortly after the downstroke begins the switch 872 (FIG. 40) opens preparing the way for later opening of the draw bars. Also, the switch 888 closes preparing the electric eye circuit for actuation. The operations above described are then repeated.

When it is desired to form packages from polyethylene film, the draw bars 52, 54 are replaced by the resistance draw bars 288, 290 as above described. The electric circuit is prepared by opening switch 936 and breaking coupling 939 and closing switches 941 and 944. Switches 938 and 940 are normally closed when using either type of draw bars.

The machine is set into operation again by closing switch 932. Operation of the machine is the same as described above insofar as actuation of the air motor 62 for the draw bars and air motor 632 for the web brake are concerned. The impulse heater circuit for the draw bars is actuated by closure of switch 954 when the draw bars 288, 290 are fully closed. The triggering circuit 949 actuates the timer 946 which then passes a short pulse of current through the relay R-6. Contacts R-6-1 are thus momentarily closed, permitting a short pulse of current to flow through the resistance wire 384. This pro-

vides sufficient heat to heat-seal and transversely seam the polyethylene tube T_p which is then severed intermediate this heat-sealed area by the heated wire 329. It will again be noted that when current is fed to the wire 384, the portion of the tube T_p engaged thereby is relieved of tension stresses by the above-described mounting of the grippers 393 and 368, wire 384 and pressure member 329. With this arrangement a tight seal is reliably formed each time.

During the upstroke of the draw bars the long seam sealer is swung into contact with the wrapper tube and then the switch 898 is closed. Relay R-5 and its contacts R-5-1 close momentarily and a pulse of current is fed to the ribbon 709 which will heat-seal the lapped portions of the web and complete the wrapper tube.

Summary

The above-described machine has been found highly effective in giving higher rates of operation and greater versatility than any previous machine designed for the same purposes. It is, of course, to be recognized that where the use of the machine is for more specialized purposes, greater economies can be had, particularly in machine cost and simplification, by omitting certain of the cooperative mechanisms.

Other features of the machine will also find utility apart from the combination herein disclosed. Further, much of the mechanism, particularly that employed in moving the draw bars, can be advantageously employed in a "horizontal flow" machine as opposed to what would herein be termed a "vertical flow" machine.

Also, it is possible to use glue or other means for seaming the wrapper tube and still enjoy many advantages of the inventive features herein disclosed.

In any event, the scope of the inventive concepts is to be derived from the following claims.

Having thus disclosed the invention, what is claimed as novel and desired to be secured by Letters Patent of the United States is:

1. In a packaging machine, a pair of draw bars, a swinging arm comprising a bracket and a pair of parallel rods projecting therefrom, said draw bars being slidably mounted on said rods, means for moving said draw bars on said rods between an open position and a closed gripping position and linkage means for mounting said arm and constraining movement of said draw bars to a substantially straight line path in one direction when the draw bars are in their closed position, and then returning the draw bars in the opposite direction when they are in their open position.

2. In a packaging machine, a pair of draw bars, a swinging arm comprising a bracket and a pair of parallel cantilever rods of uniform diameter projecting therefrom, said draw bars being slidably mounted on said rods, means for moving said draw bars on said rods between an open position and a closed gripping position, said moving means comprising a link pivotally connected with each end of each draw bar and a removable pin effecting the pivotal connection of each of said links to said draw bars, whereby said pins may be readily removed to facilitate removal of said draw bars from the free ends of said rods, and linkage means for mounting said arm and constraining movement of said draw bars to a substantially straight line path in one direction when the draw bars are in their closed position, and then returning the draw bars in the opposite direction when they are in their open position.

3. In a packaging machine, a pair of draw bars, a swinging arm comprising a bracket and a pair of parallel rods projecting therefrom, said draw bars being slidably mounted on said rods, means mounted on said bracket for moving said draw bars on said rods between an open position and a closed gripping position, and linkage means for mounting said arm and constraining movement of said draw bars to a substantially straight line path in one direction when the draw bars are in their closed position.

tion, and then returning the draw bars in the opposite direction when they are in their open position.

4. In a packaging machine, a pair of draw bars, a swinging arm comprising a bracket and a pair of parallel rods projecting therefrom, said draw bars being slidably mounted on said rods, a fluid motor mounted on said bracket, means connected to and responsive to actuation of said fluid motor for moving said draw bars on said rods between an open position and a closed gripping position, and linkage means for mounting said swinging arm and constraining movement of said draw bars to a substantially straight line path in one direction when the draw bars are in their closed position, and then returning the draw bars in the opposite direction when they are in their open position.

5. In a packaging machine having frame members, a pair of draw bars, a swinging arm comprising a bracket and a pair of parallel cantilever rods projecting therefrom, said draw bars being slidably mounted on said rods, means mounted on said bracket for moving said draw bars on said rods between an open position and a closed gripping position, linkage means including a rotating crank for mounting said arm and constraining movement of said draw bars to a substantially straight line path in one direction when they are in their gripping position and then returning the draw bars in the opposite direction when they are in their open position, a transverse shaft journaled at the rear of said bracket, a link pivotally connected to said transverse shaft adjacent each end thereof and pivotally mounted on a frame member at a point spaced therefrom generally transverse to the plane of the swinging arm, said links being a part of said linkage means, said linkage means further including a second pair of links pivotally connected to the front of said bracket at opposite sides thereof, each of said second pair of links being pivotally mounted on a frame member at a point spaced forwardly of said bracket and generally in the plane of the swinging arm, said draw bar moving means including a fluid motor pivotally mounted on said bracket and having a reciprocable piston rod, a lever arm fast on said transverse shaft and connected to the piston rod of said fluid motor, a double-ended lever secured to said transverse shaft adjacent each end thereof, a link connecting one end of each of said double-ended levers to the adjacent end of one of said draw bars, a link connecting the opposite end of each of said double-ended levers to the adjacent end of the other of said draw bars whereby the draw bars will be moved simultaneously towards and away from each other when said fluid motor is actuated.

6. In a packaging machine, a pair of draw bars, a swinging arm comprising a bracket and a pair of parallel cantilever rods projecting therefrom, said draw bars being slidably mounted on said rods, means mounted on said bracket for moving said draw bars on said rods between an open position and a closed gripping position, linkage means including a rotating crank for mounting said arm and constraining movement of said draw bars to a substantially straight line path in one direction when the draw bars are in their closed position, and then returning the draw bars in the opposite direction when they are in their open position, and means for varying the effective throw of said rotating crank to thereby vary the stroke of said draw bars between said upper and lower limits.

7. The apparatus of claim 6 wherein the adjustable through crank comprises a first arm secured to a crank shaft, a second arm telescoped over the end of said shaft, a shear screw securing said first and second arms together.

8. The apparatus of claim 7 wherein a link is pivotally connected at one end to said bracket, a slide block is pivotally connected to the other end of said bracket, said second arm having a guideway formed radially of said shaft for receiving said slide block and screw means for adjusting said slide block along the length of said guideway.

9. In a packaging machine, a pair of draw bars, a swinging arm comprising a bracket and a pair of parallel cantilever rods projecting therefrom, said draw bars being slidably mounted on said rods, means mounted on said bracket for moving said draw bars on said rods between an open position and a closed gripping position, linkage means including a rotating crank for mounting said arm and constraining movement of said draw bars to a substantially straight line path in one direction when the draw bars are in their closed position, and then returning the draw bars in the opposite direction when they are in their open position, and means for varying the effective throw of said rotating crank to thereby vary the stroke of said draw bars in said one direction, and means for varying the rate of rotation of said crank.

10. In a packaging machine, a pair of draw bars, a swinging arm comprising a bracket and a pair of parallel cantilever rods projecting therefrom, said draw bars being slidably mounted on said rods, means mounted on said bracket for moving said draw bars on said rods between an open position and a closed gripping position, linkage means, including a rotating crank, for mounting said arm and constraining movement of said draw bars to a substantially straight line path in one direction when the draw bars are in their closed position, and then returning the draw bars in the opposite direction when they are in their open position, and means for varying the effective throw of said rotating crank to thereby vary the stroke of said draw bars in said one direction, means for varying the rate of rotation of said crank, said linkage means including a link connecting said bracket and said crank, and means for varying the effective length of said link whereby a fixed limit of movement of the draw bars in one direction may be maintained regardless of variations in the length of stroke of the draw bars.

11. In a packaging machine, a pair of draw bars, a swinging arm comprising a bracket and a pair of parallel cantilever rods projecting therefrom, said draw bars being slidably mounted on said rods, means mounted on said bracket for moving said draw bars on said rods between an open position and a closed gripping position, means for adjusting the extent of movement of and the distance between said draw bars in their open position, linkage means including a rotating crank for mounting said arm and constraining movement of said draw bars to a substantially straight line path in one direction when the draw bars are in their closed position, and then returning the draw bars in the opposite direction when they are in their open position, and means for varying the effective throw of said rotating crank to thereby vary the stroke of said draw bars in said one direction, and means for varying the rate of rotation of said crank.

12. In a packaging machine having frame members, a pair of draw bars, a swinging arm comprising a bracket and a pair of cantilever rods projecting therefrom, said draw bars being slidably mounted on said rods, means mounted on said bracket for moving said draw bars on said rods between an open position and a closed gripping position, linkage means including a rotating crank for mounting said arm and constraining movement of said draw bars to a substantially straight line path in one direction when the draw bars are in their gripping position, and then returning the draw bars in the opposite direction when they are in their open position, a transverse shaft journaled at the rear of said bracket, a link pivotally connected to said transverse shaft adjacent each end thereof and pivotally mounted on a frame member at a point spaced therefrom generally transverse to the plane of the swinging arm, said links being a part of said linkage means, said linkage means further including a second pair of links pivotally connected to the front of said bracket at opposite sides thereof, each of said second pair of links being pivotally mounted on a frame member at a point spaced forwardly of said bracket and

generally in the plane of the swinging arm, means for varying the effective throw of said rotating crank to thereby vary the stroke of said draw bars in said one direction, means for varying the rate of rotation of said crank, 5 said draw bar moving means including a fluid motor pivotally mounted on said bracket and having a reciprocating piston rod, a lever arm fast on said transverse shaft and pivotally connected to said piston rod, a double-ended lever secured to said transverse shaft adjacent each 10 end thereof, a link connecting one end of each of said double-ended levers to the adjacent end of one of said draw bars, a link connecting the opposite end of each of said double-ended levers to the adjacent end of the other of said draw bars whereby the draw bars will be 15 moved simultaneously towards and away from each other when said fluid motor is actuated, and means for varying the effective stroke of said fluid motor to thereby vary the extent of movement of said draw bars on said rods and the distance therebetween in their open position.

20 13. In a packaging machine, a pair of draw bars, a swinging arm comprising a bracket and a pair of parallel rods projecting therefrom, said draw bars being slidably mounted on said rods, means for moving said draw bars on said rods between an open position and a closed gripping position wherein the draw bars are clamped against a tube of wrapper material, linkage means for mounting said arm and constraining movement of said draw bars to a substantially straight line path in one direction when the draw bars are in their closed position, and then returning

25 the draw bars in the opposite direction when they are in their open position, said draw bars each having a pair of opposed heat-sealing elements longitudinally spaced relative to the wrapper tube, an elongated knife mounted on one of said draw bars and disposed between the heat-sealing elements thereof, and means mounted on said one draw bar for projecting said knife towards the other draw bar when the draw bars are in their gripping position.

14. In a packaging machine, a pair of draw bars each having a pair of opposed heat-sealing elements for trans-

40 versely seaming a tube of wrapper material, each pair of elements being longitudinally spaced relative to the wrapper tube, a swinging arm comprising a bracket and a pair of parallel rods projecting therefrom, said draw bars being slidably mounted on said rods, a fluid motor mounted on said bracket and operatively connected to said draw bars to move said draw bars on said rods between an open position and a closed gripping and heat-sealing position, linkage means for mounting said arm and constraining movement of said draw bars to a substantially straight line path in one direction when the draw bars are in their closed position, and then returning the draw bars in the opposite direction when they are in their open position, an elongated knife disposed between the heat-sealing elements of one of said draw bars, a fluid motor mounted on said one draw bar and operatively connected to said knife, and means for actuating said fluid motor to project said knife towards the other draw bar when the draw bars are in their gripping and heat-sealing position to thereby sever the tube of wrapper material intermediate the seam formed by said heat-sealing

55 15. In a packaging machine, a pair of draw bars each having a pair of opposed heat-sealing elements for trans-

60 versely seaming a tube of wrapper material, each pair of elements being longitudinally spaced relative to the wrapper tube, a swinging arm comprising a bracket and a pair of parallel rods projecting therefrom, said draw bars being slidably mounted on said rods, a first fluid motor mounted on said bracket and operatively connected to said draw bars to move said draw bars on said rods between an open position and a closed gripping and heat-sealing position, linkage means for mounting said arm and constraining movement of said draw bars to a substantially straight line path in one direction when the draw bars are in their closed position and then returning

the draw bars in the opposite direction when they are in their open position, thereby drawing successive lengths of the wrapper tube, an elongated knife disposed between the heat-sealing elements of one of said draw bars, a second fluid motor mounted on said one draw bar and operatively connected to said knife, a solenoid valve mounted on said bracket and having flexible fluid connections with said second fluid motor, an electrical circuit for actuating said solenoid valve and operating said second fluid motor to project said knife towards the other draw bar when the draw bars are in their gripping and heat-sealing position to thereby sever the tube of wrapper material intermediate the seam formed by said heat-sealing elements, said electrical circuit including a switch for completing the circuit to said solenoid valve and a remote cam controlling operation of said switch, said cam being rotatable in fixed time relation to the movement of said draw bars in their drawing direction.

16. In a packaging machine, a pair of draw bars each having a pair of opposed heat-sealing elements for transversely seaming a tube of wrapper material, each pair of elements being longitudinally spaced relative to the wrapper tube, a swinging arm comprising a bracket and a pair of parallel rods projecting therefrom, said draw bars being slidably mounted on said rods, a first air motor mounted on said bracket and operatively connected to said draw bars to move said draw bars on said rods between an open position and a closed gripping and heat-sealing position, linkage means for mounting said arm and constraining movement of said draw bars to a substantially straight line path in one direction when the draw bars are in their closed position and then returning the draw bars in the opposite direction when they are in their open position, thereby drawing successive lengths of the wrapper tube, an elongated knife mounted on one of said draw bars and disposed between the heat-sealing elements thereof, said knife having a serrated cutting edge, a second air motor mounted on said one draw bar and operatively connected to project said knife towards the other draw bar a distance sufficient to sever a tube of wrapper material gripped therebetween, means for limiting the movement of said knife towards said other draw bar to a position preventing severance of said tube and permitting penetration thereof by the serrated cutting edge of the knife whereby the web will be perforated, and means for periodically rendering said last-named means inoperative whereby the tube of wrapper material will be severed.

17. In a packaging machine, a pair of draw bars each having a pair of opposed heat-sealing elements for transversely seaming a tube of wrapper material, each pair of elements being longitudinally spaced relative to the wrapper tube, a swinging arm comprising a bracket and a pair of parallel rods projecting therefrom, said draw bars being slidably mounted on said rods, a first air motor mounted on said bracket and operatively connected to said draw bars to move said draw bars on said rods between an open position and a closed gripping and heat-sealing position, linkage means for mounting said arm and constraining movement of said draw bars to a substantially straight line path in one direction when the draw bars are in their closed position, and then returning the draw bars in the opposite direction when they are in their open position, thereby drawing successive lengths of wrapper tube, an elongated knife disposed between the heat-sealing elements of one of the draw bars, said knife having a serrated cutting edge, a U-shaped bracket connected by its arms to the ends of said knife, a second air motor mounted on said one draw bar and having a piston rod connected to the bridge of said U-shaped bracket, said piston rod having a stroke sufficient to project the knife a distance sufficient to sever a tube of wrapper material between the draw bars, means for actuating said second air motor each time the draw bars are moved to their gripping position, a third air motor

mounted on said one draw bar and having a reciprocating piston rod, a plate connected to said piston rod and movable to an obstructive position between the bridge of said U-shaped bracket and the heat-sealing elements of said one draw bar thereby limiting movement of said knife to a position wherein the wrapper tube is perforated but not severed, means for actuating said third air motor to bring said plate into said obstructive position each time the second air motor is actuated, and means for periodically rendering the actuating means for said third air motor inoperative.

18. Structure as in claim 17 wherein said one draw bar is the draw bar adjacent said bracket and wherein the actuating means for said second and third air motors comprise solenoid air valves mounted on said bracket and flexible hoses connect said valves with the second and third air motors.

19. Structure as in claim 18 wherein quick disconnect couplings are provided for attaching the flexible hoses to the solenoid valves to facilitate ready removal of the draw bars from said rods.

20. In a packaging machine, a pair of draw bars, a swinging arm comprising a bracket and a pair of parallel rods projecting therefrom, said draw bars being slidably mounted on said rods, means for moving said draw bars on said rods between an open position and a closed gripping position wherein the draw bars are clamped against a tube of wrapper material, linkage means for mounting said arm and constraining movement of said draw bars to a substantially straight line path in one direction when the draw bars are in their closed position, and then returning the draw bars in the opposite direction when they are in their open position, said draw bars each having a pair of opposed heat-sealing elements longitudinally spaced relative to the wrapper tube, an elongated knife mounted on one of said draw bars and disposed between the heat-sealing elements thereof, an air motor mounted on said one draw bar, connected to said knife and operable to sever the wrapper tube, said knife having a serrated edge, means for actuating said air motor when said draw bars are clamped against the wrapper tube, means for limiting movement of said knife to a position in which severance of the wrapper tube is prevented and the tube is perforated by the serrated edge of the knife, and means for periodically rendering said last-named means inoperative, thereby permitting severance of the tube when said air motor is actuated.

21. In a packaging machine having a pair of draw bars, means for moving the draw bars in a drawing direction and then returning them in the opposite direction, means for clamping said draw bars against a tube of wrapper material as they move in the drawing direction, said draw bars each having a pair of opposed heater elements longitudinally spaced relative to the wrapper tube for transversely seaming the tube, an elongated knife disposed intermediate the heater elements on one of said draw bars, an air motor mounted on said one draw bar connected to said knife and operable to sever the wrapper tube, said knife having a serrated edge, means for actuating said air motor when said draw bars are clamped against the wrapper tube, means for limiting movement of said knife to a position in which severance of the wrapper tube is prevented and the tube is perforated by the serrated edge of the knife, and means for periodically rendering said last-named means inoperative thereby permitting severance of the tube when said air motor is actuated.

22. In a packaging machine having a pair of draw bars, means for moving the draw bars in a drawing direction and then returning them in the opposite direction, means for clamping said draw bars against a tube of wrapper material as they move in the drawing direction, said draw bars each having a pair of opposed heater elements longitudinally spaced relative to the wrapper tube for transversely seaming the tube, an elongated knife dis-

posed intermediate the heater elements on one of said draw bars, yieldable means for projecting said knife towards said one draw bar to sever the wrapper tube clamped therebetween, means for limiting movement of said knife to a position in which severance of the wrapper tube is prevented and the tube is perforated by the serrated edge of the knife, and means for periodically rendering said last-named means inoperative thereby permitting severance of the tube when said knife projecting means is actuated.

23. In a packaging machine having a pair of draw bars for clamping and advancing a tube of polyethylene or like wrapper material, a swinging arm comprising a bracket and a pair of parallel rods projecting therefrom, said draw bars being slidably mounted on said rods, the draw bar adjacent said bracket comprising an elongated support member and an electrical resistance ribbon running therealong transversely of said wrapper tube, said support member being yieldably mounted relative to said adjacent draw bar, a pair of grippers straddling said resistance ribbon and support member and rigidly mounted on said adjacent draw bar, a pressure member rigidly mounted on the other draw bar in opposed relation to said ribbon, a second pair of grippers straddling said pressure member and yieldably mounted on said other draw bar, said yieldable grippers being spaced outwardly from said pressure member and said ribbon being spaced outwardly of said rigid grippers and means for feeding a pulse of current to said resistance ribbon when said draw bars are in their closed position.

24. Apparatus as in claim 23 wherein the pressure member comprises a resilient pad and a cut-off wire mounted in opposed relation to said ribbon and further wherein means are provided for heating said cut-off wire to a slightly elevated temperature.

25. Apparatus as in claim 23 wherein the fluid motor comprises a reciprocating piston rod and the means for moving the draw bars on the rods comprise a shaft journaled on the swinging arm bracket, a lever fast on the shaft and connected to said piston rod whereby reciprocation of the piston rod will cause the shaft to oscillate, a pair of matching double-ended levers secured to said shaft, a link connecting one end of each lever to the adjacent draw bar, a link connecting the other end of each lever to the other draw bar whereby oscillation of the shaft will simultaneously move the draw bars toward and away from each other, and means responsive to oscillation of said shaft bringing said draw bars to their closed position for actuating said pulse feeding means.

26. In a packaging machine having a frame member, a pair of draw bars for clamping and advancing a tube of polyethylene or like wrapper material, a swinging arm adjacent said frame member and comprising a bracket and a pair of parallel rods projecting therefrom, said draw bars being slidably mounted on said rods, the draw bar adjacent said bracket comprising an elongated support member and an electrical resistance ribbon running therealong transversely of said wrapper tube, said support member being yieldably mounted relative to said adjacent draw bar, a pair of grippers straddling said resistance ribbon and support member and rigidly mounted on said adjacent draw bar, a junction box on said adjacent draw bar, electrical connections extending from the ends of said resistance ribbon to said junction box, a second junction box mounted on said frame member, a flexible electrical cable extending from said first junction box to said second junction box and connected thereto by a quick disconnect connector unit, the other draw bar comprising an elongated pressure member rigidly mounted thereon in opposed relation to said resistance ribbon, a second pair of grippers straddling said pressure member in opposed relation to said first pair of grippers, said second pair of grippers being yieldably mounted relative to said other draw bar, said resistance ribbon lying in a plane spaced outwardly from said first pair of grippers and said second pair of grippers lying in a plane spaced outwardly of said pressure member, a fluid motor mounted on said bracket, means connected to and responsive to actuation of said fluid motor for moving said draw bars on said rods between an open position and a closed gripping position whereby the wrapper tube is first clamped by said grippers and then the tension on said tube in the portion over said resistance ribbon is relieved as the second pair of grippers and the ribbon support both yield, and linkage means for mounting said swinging arm and constraining movement of said draw bars to a substantially straight line path in one direction when the draw bars are in their closed position and then returning the draw bars in the opposite direction when they are in their open position, and means for feeding a pulse of current to said resistance ribbon when said draw bars are in their closed position.

5 said first pair of grippers and said second pair of grippers lying in a plane spaced outwardly of said pressure member, a fluid motor mounted on said bracket, means connected to and responsive to actuation of said fluid motor for moving said draw bars on said rods between an open position and a closed gripping position, whereby the wrapper tube is first clamped by said grippers and then the tension on said tube in the portion over said resistance ribbon is relieved as the second pair of grippers 10 and the ribbon support both yield, linkage means for mounting said swinging arm and constraining movement of said draw bars to a substantially straight line path in one direction when the draw bars are in their closed position, and then returning the draw bars in the opposite direction when they are in their open position, and means for feeding a pulse of current to said resistance ribbon when said draw bars are in their closed position.

15 27. In a packaging machine having a frame member, a pair of draw bars for clamping and advancing a tube of polyethylene or like wrapper material, a swinging arm adjacent said frame member and comprising a bracket and a pair of parallel rods projecting therefrom, said draw bars being slidably mounted on said rods, the draw bar adjacent said bracket comprising an elongated support member and an electrical resistance ribbon running therealong transversely of said wrapper tube, said support member having an internal passageway therethrough, tubes projecting from opposite ends of said passageway towards said bracket, flexible hoses extending from said 20 tubes towards said bracket and connected thereto by quick disconnect couplings, passageway means mounted on said bracket and extending from said quick disconnect couplings to one side of said bracket, a pair of pipes mounted on said frame member, one of which extends to 25 a source of cooling water and the other of which extends to a drain, a pair of flexible hoses connecting said pipes to the passageway forming means on said bracket thereby providing cooling water for said support member, a pair of grippers straddling said resistance ribbon and support 30 member and rigidly mounted on said adjacent draw bar, a junction box on said adjacent draw bars, electrical connections extending from the ends of said resistance ribbon to said junction box, a second junction box mounted on said frame member, a flexible electrical cable extending from said first junction box to said second junction box and connected thereto by a quick disconnect connector unit, the other draw bar comprising an elongated pressure member rigidly mounted thereon in opposed relation to said resistance ribbon, a second pair of grippers straddling said pressure member in opposed relation to said first pair of grippers, said second pair of grippers being yieldably mounted relative to said other draw bar, said resistance ribbon lying in a plane spaced outwardly from said first pair of grippers and said second pair of grippers lying in a plane spaced outwardly of said pressure member, a fluid motor mounted on said bracket, means connected to and responsive to actuation of said fluid motor for moving said draw bars on said rods between an open position and a closed gripping position whereby the wrapper tube is first clamped by said grippers and then the tension on said tube in the portion over said resistance ribbon is relieved as the second pair of grippers and the ribbon support both yield, and linkage means for mounting said swinging arm and constraining movement of said draw bars to a substantially straight line path in one direction when the draw bars are in their closed position and then returning the draw bars in the opposite direction when they are in their open position, and means for feeding a pulse of current to said resistance ribbon when said draw bars are in their closed position.

35 28. In a packaging machine having a pair of draw bars for clamping and advancing a tube of polyethylene or like wrapper material, a swinging arm comprising a bracket and a pair of parallel rods projected therefrom, said draw bars being slidably mounted on said rods, a

fluid motor mounted on said bracket, means connected to and operative in response to actuation of said fluid motor for moving the draw bars between an open position and a closed position, the draw bar adjacent said bracket comprising an elongated support member and an electrical resistance ribbon running therealong transversely of said wrapper tube, said support member being yieldably mounted relative to said adjacent draw bar, a pair of grippers straddling said resistance ribbon and support member and rigidly mounted on said adjacent draw bar, a pair of relatively thin strippers slidably mounted and interposed between said grippers and said support member, spring means urging said strippers into a position projecting beyond said grippers and said resistance wire, said strippers having lateral portions projecting beyond said grippers, said adjacent draw bar having a slot running substantially the length of said support member, two lengths of insulated cloth threaded through said slot and between said support member and one of said strippers, one length of cloth passing between said support member and said resistance ribbon and the other cloth passing over said resistance ribbon, both lengths of cloth being reversely folded around said support member and threaded between the other stripper and the support member and back through said slot, and means for releasably clamping both ends of both lengths of cloth thereby permitting successive portions of the cloth to be operatively positioned relative to said resistance ribbon, the other draw bar comprising an elongated pressure member rigidly mounted thereon in opposed relation to said resistance ribbon, a second pair of grippers straddling said pressure member in opposed relation to said first pair of grippers, said second pair of grippers being yieldably mounted relative to said other draw bar, said resistance ribbon lying in a plane spaced outwardly from said first pair of grippers and said second pair of grippers lying in a plane spaced outwardly of said pressure member, said other draw bar having means engageable with the projecting portions of said strippers prior to engagement of the grippers with the wrapper tube when the draw bars are moved toward their closed position whereby when the draw bars are closed the wrapper tube is first clamped by said grippers and then the tension on said tube in the portion over said resistance ribbon is released as the second pair of grippers and the wire support both yield a length, means for mounting said swinging arm and constraining movement of said draw bars to a substantially straight line path in one direction when the draw bars are in their closed position and then returning the draw bars in the opposite direction when they are in their open position, and means for feeding a pulse of current to said resistance ribbon when said draw bars are in their closed position.

29. In a packaging machine, a pair of draw bars movable to clamp and advance a tube of polyethylene or like wrapper material, a pressure member elongated transversely of the wrapper web and rigidly mounted on one draw bar, a heat-sealing member comprising a resistance ribbon opposed to said pressure member and a backup plate therefor, said backup plate being yieldingly mounted on the other of said draw bars, said other draw bar having a slot aligned with said backup plate, a length of protective sheet material doubled over said resistance ribbon and backup plate with its ends threaded through said slot, means projecting from the backup plate and through said slot for releasably clamping said protective material in taut condition over said resistance ribbon, a pair of grippers rigidly mounted on said other draw bar and straddling said heat-sealing member, the latter member lying in a plane spaced outwardly from said grippers, a second pair of opposed grippers straddling the pressure member and yieldingly mounted on said one draw bar, said second pair of grippers being spaced outwardly from said pressure member, a stripper interposed between each of the first grippers and the backup plate, spring means urging

said strippers to a position projecting beyond said first grippers and said heat-sealing member, and means mounted on said one draw bar for displacing said strippers from said projecting position as the draw bars are moved to clamp the wrapper tube.

5 30. In a packaging machine, a pair of draw bars movable to clamp and advance a tube of polyethylene or like wrapper material, a pressure member elongated transversely of the wrapper tube and mounted on one of said draw bars, a heat-sealing member opposed thereto and comprising a resistance ribbon mounted on the other of said draw bars, one of said members being yieldable relative to the draw bar on which it is mounted and the other of said members being relatively rigid with respect to the draw bar on which it is mounted, a pair of opposed grippers straddling each of said members and respectively mounted on one and the other of said draw bars, the pair of grippers straddling the relatively rigidly mounted member being yieldable relative to the draw bar on which it is mounted, the yieldably mounted grippers lying in a plane spaced outwardly of the relatively rigid member, the pair of grippers straddling the yieldable member being relatively rigidly mounted on the other draw bar, the yieldable member lying in a plane outwardly of the relatively rigid grippers, a pair of strippers on one draw bar interposed between one of said members and the pair of grippers straddling same, spring means urging said strippers to a position projecting beyond said member and grippers, and means mounted on the other draw bar for displacing said strippers from said projecting position as the draw bars are moved to clamp the wrapper tube.

31. In a packaging machine, a pair of draw bars movable to clamp and advance a tube of polyethylene or like wrapper material, a pressure member elongated transversely of the wrapper tube and mounted on one of said draw bars, a heat-sealing member opposed thereto and comprising a resistance ribbon and a backup plate therefor mounted on the other of said draw bars, one of said members being yieldable relative to the draw bar on which it is mounted, and the other of said members being relatively rigid with respect to the draw bar on which it is mounted, a pair of opposed grippers straddling each of said members and respectively mounted on one and the other of said draw bars, the pair of grippers straddling the relatively rigidly mounted member being yieldable relative to the draw bar on which it is mounted, the yieldably mounted grippers lying in a plane spaced outwardly of the relatively rigid member, the pair of grippers straddling the yieldable member being relatively rigidly mounted on the other draw bar, the yieldable member lying in a plane outwardly of the relatively rigid grippers, said other draw bar having a slot aligned with said backup plate, a length of protective sheet material threaded through said slot between said backup plate and one of said grippers and over said resistance wire and then threaded between the backup plate and the other adjacent gripper and through the slot, means spaced outwardly of said draw bars for releasably clamping opposite ends of said protective material whereby successive lengths of said material can readily be positioned over said resistance wire.

32. In a packaging machine, a pair of draw bars movable to clamp and advance a tube of polyethylene or like wrapper material, a pressure member elongated transversely of the wrapper tube and mounted on one of said draw bars, a heat-sealing member opposed thereto and comprising a resistance ribbon mounted on the other of said draw bars, one of said members being yieldable relative to the draw bar on which it is mounted and the other of said members being relatively rigid with respect to the draw bar on which it is mounted, a pair of opposed grippers straddling each of said members and respectively mounted on one and the other of said draw bars, the pair of grippers straddling the relatively rigidly

mounted member being yieldable relative to the draw bar on which it is mounted, the yieldably mounted grippers lying in a plane spaced outwardly of the relatively rigid member, the pair of grippers straddling the yieldable member being relatively rigidly mounted on the other draw bar, the yieldable member lying in a plane outwardly of the relatively rigid grippers.

33. In a packaging machine, a pair of draw bars movable to clamp and advance a tube of polyethylene or like wrapper material, a pressure member mounted on one of said draw bars and comprising a resilient pad elongated transversely of the wrapper tube and a cut-off wire running the length of said pad, a heat-sealing member mounted on the other of said draw bars and comprising a resistance ribbon opposed to said wire, means for heating said cut-off wire to a slightly elevated temperature and means for feeding a pulse of current to said ribbon when the draw bars are clamped against the wrapper tube, one of said members being yieldable relative to the draw bar on which it is mounted and the other of said members being relatively rigid with respect to the draw bar on which it is mounted, a pair of opposed grippers straddling each of said members and respectively mounted on one and the other of said draw bars, the pair grippers straddling the relatively rigidly mounted member being yieldable relative to the draw bar on which it is mounted, the yieldably mounted grippers lying in a plane spaced outwardly of the relatively rigid member, the pair of grippers straddling the yieldable member being relatively rigidly mounted on the other draw bar, the yieldable member lying in a plane outwardly of the relatively rigid grippers.

34. In a packaging machine, a pair of draw bars movable to clamp and advance a tube of polyethylene or like wrapper material, a pressure member mounted on one of said draw bars and comprising a resilient pad elongated transversely of the wrapper tube and a cut-off wire running the length of said pad, a heat-sealing member mounted on the other of said draw bars and comprising a resistance ribbon opposed to said wire, means for heating said cut-off wire to a slightly elevated temperature and means for feeding a pulse of current to said ribbon when the draw bars are clamped against the wrapper tube.

35. In a packaging machine having a pair of draw bars for clamping and intermittently advancing a tube of polyethylene or like wrapper material, a tubular former over which a web of the wrapper material is drawn in forming the wrapper tube, the marginal edges of the wrapper web being lapped longitudinally of said former, a frame pivotally mounted on said machine for movement toward and away from said former, a longitudinal seam sealer comprising a resistance ribbon mounted on said frame in opposed relation to the lapped wrapper portions, means for swinging the frame toward the former and pressing the ribbon against said lapped portions when the wrapper is at rest on the former, means for feeding a pulse of current to said ribbon when it is pressed against said lapped portions, a swinging arm comprising a bracket having a pair of parallel rods projecting therefrom, said draw bars being slidably mounted on said rods, the draw bar adjacent said bracket comprising an elongated support member and an electrical resistance ribbon running therealong transversely of said wrapper tube, said support member being yieldably mounted relative to said adjacent draw bar, a pair of grippers straddling said resistance ribbon and support member and rigidly mounted on said adjacent draw bar, the other draw bar comprising an elongated pressure member rigidly mounted thereon in opposed relation to the resistance ribbon on said adjacent draw bar, a second pair of grippers straddling said pressure member in opposed relation to said first pair of grippers, said second pair of grippers being yieldably mounted relative to said other draw bar, the resistance ribbon on said adjacent draw bar lying in a plane spaced outwardly from said first pair of grippers and

said second pair of grippers lying in a plane spaced outwardly of said pressure member, a fluid motor mounted on said bracket, means connected to and responsive to actuation of said fluid motor for moving said draw bars on said rods between an open position and a closed gripping position whereby the wrapper tube is first clamped by said grippers and then the tension on said tube in the portion over the resistance ribbon on the adjacent draw bar is released as the second pair of grippers and the said ribbon support both yield, linkage means for mounting said swinging arm and constraining movement of said draw bars to a substantially straight line path away from said former and then returning the draw bars towards said former when they are in their open position, and means for feeding a pulse of current to the resistance ribbon on said adjacent draw bar when said draw bars are in their closed position.

36. In a packaging machine, a pair of draw bars, a swinging arm comprising a bracket and a pair of parallel rods projecting therefrom, said draw bars being slidably mounted on said rods, a reciprocating air motor mounted on said bracket, means connected to and responsive to actuation of said air motor for moving said draw bars on said rods between an open position and a closed gripping position, linkage means including a rotating crank for mounting said swinging arm and constraining movement of said draw bars to a substantially straight line path in one direction when the draw bars are in their closed position and then returning the draw bars in the opposite direction when they are in their open position, means for varying the rate of rotation of said rotating crank and thereby varying the rate of to and fro movement of said draw bars, a cam rotated at the same rate as said crank, a control switch actuated by the working surfaces of said cam, a solenoid air valve operatively connected to said switch and said air motor and responsive to actuation of said switch to actuate said air motor for closing movement of said draw bars and means for adjusting the angular relation of said switch relative to the working surfaces of said cam to thereby adjust the relative time of actuation of said air motor.

37. In a packaging machine, a pair of draw bars, a swinging arm comprising a bracket and a pair of parallel rods projecting therefrom, said draw bars being slidably mounted on said rods, a reciprocating air motor mounted on said bracket, means connected to and responsive to actuation of said air motor for moving said draw bars on said rods between an open position and a closed gripping position, linkage means including a rotating crank for mounting said swinging arm and constraining movement of said draw bars to a substantially straight line path in one direction when the draw bars are in their closed position, and then returning the draw bars in the opposite direction when they are in their open position, means for varying the rate of rotation of said rotating crank and thereby varying the rate of to and fro movement of said draw bars, a spiral cam rotated at the same rate as said crank, a control switch actuated by the working surfaces of said cam, a solenoid air valve operatively connected to said switch and said air motor and responsive to actuation of said switch to actuate said air motor for closing movement of said draw bars and means for adjusting said switch longitudinally of said cam to thereby adjust the angular relation of said switch to the working surfaces of said cam and also the relative time of actuation of said air motor.

38. In a packaging machine, a pair of draw bars, a swinging arm comprising a bracket and a pair of parallel rods projecting therefrom, said draw bars being slidably mounted on said rods, a reciprocating air motor mounted on said bracket, means connected to and responsive to actuation of said air motor for moving said draw bars on said rods between an open position and a closed gripping position, linkage means including a rotating crank for mounting said swinging arm and constraining move-

ment of said draw bars to a substantially straight line path in one direction when the draw bars are in their closed position and then returning the draw bars in the opposite direction when they are in their open position, means for varying the rate of rotation of said crank and thereby varying the rate of to and fro movement of said draw bars, first and second cams rotated at the same rate as said crank, a first control switch actuated by the working surfaces of said first cam, a second control switch actuated by the working surfaces of said second cam, a four-way solenoid air valve operatively connected to said switches and said air motor and responsive to actuation of said first switch to actuate said air motor for closing movement of said draw bars and responsive to actuation of said second switch to actuate said air motor for opening movement of said draw bars and means for independently adjusting the angular relation of said first and second switches relative the working surfaces of said first and second cams respectively to thereby adjust the relative time of actuation of said air motor for opening and closing the draw bars.

39. In a packaging machine, means for forming a tube of wrapper material from a wrapper web having indicia spaced apart thereon a distance reflecting the length of package to be formed, a pair of draw bars for gripping and advancing the wrapper tube, a swinging arm comprising a bracket and a pair of parallel rods projecting therefrom, said draw bars being slidably mounted on said rods, a reciprocating air motor mounted on said bracket, means connected to and responsive to actuation of said air motor for moving said draw bars on said rods between an open position and a closed position wherein the wrapper tube is clamped therebetween, linkage means including a rotating crank for mounting said swinging arm and constraining movement of said draw bars to a substantially straight line path in one direction when the draw bars are in their closed position, and then returning the draw bars in the opposite direction when they are in their open position, means for varying the rate of rotation of said crank and thereby varying the rate of to and fro movement of said draw bars, a first cam rotated at the same rate as said crank, a first control switch actuated by the working surfaces of said first cam, a four-way solenoid air valve operatively connected to said first and said air motor and responsive to actuation of said first switch to actuate said air motor for closing movement of said draw bars, an electric eye mechanism for detecting the indicia on said wrapper web, means responsive to detection of an indicium by said electric eye for actuating said solenoid valve to open said draw bars, the travel of said draw bars in said one direction being greater than the package length reflected by the distance between adjacent indicia, a second cam rotated at the same rate as said crank, a second control switch actuated by the working surfaces of said second cam, said second control switch being operatively connected to said solenoid valve, said solenoid valve being alternatively responsive to actuation of said second control switch to actuate said air motor for opening movement of said draw bars, means for adjusting the angular relation of said first control switch relative to said first cam whereby the time of actuation of said air motor in a closing direction will result in the wrapper tube being clamped at the extreme beginning of the movement of the draw bars in said one direction, independent means for adjusting the angular relation of said second switch relative to said second cam whereby the relative time of actuation of said air motor in an opening direction will result in release of the wrapper tube at the end of movement of the draw bar in said one direction in the event of a failure in the electric eye mechanism.

40. In a packaging machine having means for guiding a web of wrapper material to the upper end of vertically disposed wrapper tube forming means, said web having indicia spaced therealong reflecting the length of

package to be formed; a pair of draw bars for clamping the wrapper tube and drawing it from said tube forming means, a web brake for clamping said wrapper web, a first air motor for actuating said web brake, a swinging arm comprising a draw bar and a pair of parallel rods projecting therefrom, said draw bars being slidably mounted on said rods, a second air motor mounted on said bracket, means connected to and responsive to actuation of said second air motor for moving said draw bars on said arms between an open position and a closed position wherein the wrapper tube is clamped therebetween, linkage means including a rotating crank for mounting said swinging arm and constraining movement of said draw bars to a straight line downward path when the draw bars are clamped against the wrapper tube and then returning the draw bars upwardly when the draw bars are in their open position, means for varying the rate of rotation of said crank and thereby varying the rate of vertical to and fro movement of said draw bars, a first cam rotated at the same rate as said crank, a first control switch actuated by the working surfaces of said first cam, a four-way solenoid air valve operatively connected to said first switch and said air motor and responsive to actuation of said first switch for actuating said air motor for closing movement of said draw bars, an electric eye circuit energizable by detection of an indicium on said wrapper web, means responsive to energization of said electric eye circuit for actuating said solenoid valve to open said draw bars, the travel of said draw bars in the downward direction being greater than the package length reflected by the distance between adjacent indicia, means also responsive to energization of said electric eye for actuating said web brake, a second cam rotated at the same rate as said crank, a second control switch actuated by the working surfaces of said second cam, said second control switch being operatively connected to said solenoid valve, said solenoid valve being alternately responsive to actuation of said second control switch to actuate said air motor for opening movement of said draw bars, means for adjusting the angular relation of said first control switch relative to said first cam whereby the time for actuation of said air motor in a closing direction will result in the wrapper tube being clamped at the extreme beginning of the movement of the draw bars in a downward direction, independent means for adjusting the angular relation of said second switch relative to the second cam whereby the relative time of actuation of said air motor in an opening direction will result in release of the wrapper tube at the end of the movement of the draw bars in a downward direction in the event of failure in the electric eye circuit.

41. Apparatus as in claim 40 wherein a third cam is rotated at the same rate as said crank, a third switch is actuated by said third cam, means responsive to actuation of said third switch and providing an alternate means for actuating said web brake while the draw bars are moving upwardly and means are provided for de-energizing said electric eye circuit during the initial portion of the movement of the draw bars in an upward direction.

42. In a packaging machine having frame members; a pair of draw bars, a swinging arm comprising a bracket and a pair of parallel cantilever rods projecting therefrom, said draw bars being slidably mounted on said rods, a shaft journaled adjacent the rear of said bracket, an air motor pivotally mounted on said bracket and having a reciprocating piston rod, an arm fast on said shaft and connected to said piston rod, a double-ended lever secured to said shaft adjacent each end thereof, a link connecting one end of each lever to one of said draw bars, a link connecting the other end of each lever to the other draw bar, whereby actuation of said air motor will result in the draw bars moving between an open position and a closed gripping position, said links being

connected to said draw bars by removable pins whereby the draw bars may be readily removed from said rods, linkage means connected to said shaft and including a rotating crank for mounting said swinging arm and constraining movement of said draw bars to a substantially straight line path in one direction when the draw bars are in their closed position and then returning the draw bars in the opposite direction when they are in their open position, means for varying the rate of rotation of said crank and thereby varying the rate of to and fro movement of said draw bars, first and second cams rotated at the same rate as said crank and mounted on said machine at a point remote from said swinging arm, a first control switch actuated by the working surface of said first cam, a second control switch actuated by the working surfaces of said second cam, a four-way solenoid valve mounted on said bracket and having flexible air connections with opposite ends of said air motor, a flexible air hose extending from an adjacent frame member to said valve, electrical connections between said switches and valve including a flexible cable from the frame member to said bracket, said electrical connections being arranged so that actuation of one switch actuates said valve and motor for opening movement of the draw bars when they commence movement in said opposite direction and actuation of said second switch actuates said valve and motor for closing movement of the draw bars with the draw bars clamping the wrapper tube as they begin movement in said one direction.

43. Apparatus as in claim 42 wherein a flexible electrical cable extends from the frame member to the draw bar, a junction box is mounted on the frame adjacent the draw bar, the cable is joined to the junction box by a quick disconnect connector unit, and means are provided for supplying current through said cable for heating a heat-sealing member carried by at least one draw bar for transversely seaming the wrapper tube.

44. Apparatus as in claim 43 wherein the heat-sealing member on the adjacent draw bar comprises a pair of heat-sealing grippers spaced apart longitudinally of the wrapper web, a cut-off knife is disposed between said grippers, a second air motor is mounted on said draw bar and operatively connected to said knife, a second solenoid valve is mounted on said bracket and a flexible air hose extends from said second air motor and is connected to said second air motor by a quick disconnect coupling, said second valve also being connected to the flexible air hose between the frame and bracket, and means are provided for actuating said second valve to actuate said second air motor for movement of the knife towards the other draw bar when the draw bars are in their closed position to thereby sever the wrapper tube clamped therebetween.

45. In a packaging machine having means for forming a vertically disposed tube of wrapper material from a wrapper web having indicia spaced apart thereon a distance reflecting the length of package to be formed, a web brake for clamping the wrapper web, a first air motor for actuating said web brake, a pair of draw bars, means for moving the draw bars up and down, means for varying the rate of up and down movement, a second air motor operatively connected to said draw bars for opening the draw bars and then clamping them against the wrapper tube, a first control cam rotated once for each cycle of up and down movement, a switch actuated by the working surfaces of said cam, a second cam also rotated once for each cycle of up and down movement, a second control switch actuated by the working surfaces of said second cam, a four-way solenoid air valve operatively connected to said first and second switches and said air motor and responsive to actuation of said first switch for actuating said air motor for closing movement of said draw bars, an electric eye circuit energizable by detection of an indicia on said web, means responsive to energization of said electric eye circuit for

actuating said solenoid valve for opening movement of said draw bars, the travel of said draw bars in the downward direction being greater than the package length reflected by the distance between adjacent indicia, means 5 also responsive to energization of said electric eye for actuating said electric web brake, said solenoid valve being alternately responsive to actuation of said second control switch to actuate said air motor for opening movement of said draw bars, means for adjusting the 10 angular relation of said first control switch relative to said first cam whereby the time for actuation of said air motor in a closing direction will result in the wrapper tube being clamped at the extreme beginning of movement of the draw bars in a downward direction, independent 15 means for adjusting the angular relation of said second switch relative to said second cam whereby the relative time of actuation of said air motor in an opening direction will result in release of the wrapper tube at the end of the movement of the draw bars in a downward direction in the event of a failure in the electric eye circuit.

46. Apparatus as in claim 45 wherein a third cam is rotated once for each cycle of up and down movement, a third switch actuated by said third cam, means responsive to actuation of said third switch provide alternate means for actuating said web brake while the draw bars are moving upwardly, and means are provided for de-energizing said electric eye circuit during the initial portion of the movement of the draw bars in an upward direction.

47. In a packaging machine, a pair of draw bars, means for moving the draw bars to and fro in a given cycle of operation, means for varying the rate of to and fro movement of said draw bars, an air motor operatively 35 connected to the draw bars for opening and closing the draw bars, first and second cams each rotated once for each cycle of to and fro movement of the draw bars, a first control switch actuated by the working surfaces of said first cam, a second control switch actuated by the 40 working surfaces of said second cam, a four-way solenoid air valve operatively connected to said switches and said air motor and responsive to actuation of said first switch to actuate said air motor for closing movement of said draw bars and responsive to actuation of said second switch to actuate said air motor for opening movement of said draw bars and means for independently adjusting the angular relation of said first and second switches relative to the working surfaces of said first and second cams respectively to thereby adjust the relative time of 45 actuation of said air motor for opening and closing the draw bars.

48. In a packaging machine, a pair of draw bars, means for moving the draw bars to and fro in a given cycle of operation, means for varying the rate of to and fro movement of said draw bars, an air motor operatively 55 connected to the draw bars for opening and closing the draw bars, a spiral cam rotating at a constant rate once for each cycle of to and fro movement, a switch actuated by the working surfaces of said cam, a solenoid valve operatively connected to said switch and said air motor for actuation of said motor to close said draw bars in response to actuation of said switch, means for adjusting the switch longitudinally of said cam thereby adjusting the angular relation of the switch relative to the working surfaces of the cam and the relative time of actuation of said air motor in the cycle of to and fro movement.

49. In a packaging machine, a pair of draw bars, means for moving the draw bars to and fro in a given cycle of operation, means for varying the rate of to and fro movement of said draw bars, an air motor operatively 70 connected to said draw bars for closing the draw bars, a cam rotating at a constant rate once for each cycle of to and fro movement, a switch actuated by the working surfaces of said cam, a solenoid valve operatively 75

connected to said switch and said air motor for actuation of said air motor to close said draw bars in response to actuation of said switch and means, operable while the draw bars are moving to and fro, for adjusting the angular relation of said switch relative to the working surfaces of said cam to thereby adjust the time of actuation of said air motor.

50. In a packaging machine, vertically disposed means for forming a tube of wrapper material, means for mounting a supply roll of wrapper material and leading a web therefrom to the upper end of said forming means, a pair of draw bars for clamping and drawing the wrapper tube from the forming means, a swinging arm comprising a bracket and a pair of parallel rods projecting therefrom, said draw bars being slidably mounted on said rods, means for moving said draw bars on said rods between an open position and a closed position wherein the wrapper tube is clamped in a position aligned with the axis of said tube, linkage means for mounting said arm and constraining downward movement of said draw bars to a substantially straight vertical path when the draw bars are in their closed position, and then moving the draw bars upwardly when they are in their open position.

51. In a packaging machine, vertically disposed means for forming a tube of wrapper material, means for mounting a supply roll of wrapper material and leading a web therefrom to the upper end of said forming means, a take-off roll between said supply roll and said forming means around which the web is trained in an inverted loop, a pair of draw bars for clamping and drawing the wrapper tube from the forming means, a swinging arm comprising a bracket and a pair of parallel rods projecting therefrom, said draw bars being slidably mounted on said rods, means for moving said draw bars on said rods between an open position and a closed position wherein the wrapper tube is clamped in a position aligned with the axis of said tube, linkage means for interconnecting said take-off roll and said swinging arm and moving the take-off roll in the same direction as the arm, and linkage means for mounting said arm and constraining downward movement of said draw bars to a substantially straight vertical path in a downward direction when the draw bars are in their closed position, and then returning the draw bars upwardly when they are in their open position, whereupon the take-off roll will draw a further length of web from the supply roll.

52. In a packaging machine vertically disposed means for forming a tube of wrapper material, means for mounting a supply roll of wrapper material and leading a web therefrom to the upper end of said forming means, a take-off roll between said supply roll and said forming means around which the web is trained in an inverted loop, a web brake engageable with said web between said take-off roll and said tube forming means, a pair of draw bars for clamping and drawing the wrapper tube from the forming means, a swinging arm comprising a bracket and a pair of parallel rods projecting therefrom, said draw bars being slidably mounted on said rods, means for moving said draw bars on said rods between an open position and a closed position wherein the wrapper tube is clamped in a position aligned with the axis of said tube, linkage means for interconnecting said take-off roll and said swinging arm and moving the take-off roll in the same direction as the arm, linkage means for mounting said arm and constraining downward movement of said draw bars to a substantially straight vertical path when the draw bars are in their closed position, and then returning the draw bars upwardly when they are in their open position, and means for actuating said web brake to grip said web when the draw bars are moved out of their closed position whereupon the take-off roll will draw a further length of web from the supply roll as the swinging arm moves upwardly.

53. In a packaging machine, vertically disposed means

for forming a tube of wrapper material, means for mounting a supply roll of wrapper material and leading a web therefrom to the upper end of said forming means, a supply roll brake comprising a slackener roll around which the web is looped, a pair of arms pivotally mounted adjacent the supply roll axis with the slackener roll journaled at the ends thereof, a control lever having a curved cam path formed thereon eccentrically of the axis of said arms, a member projecting from one of said arms and engageable with said cam track, a brake drum rotatable with said supply roll, a brake member mounted on said lever and engageable with said drum, the eccentricity of said cam path being such that as the loop around the slackener roll decreases, the brake is gradually disengaged from said brake drum, a take-off roll between said slackener roll and said forming means around which the web is trained in an inverted loop, a web brake engageable with said web between said take-off roll and said tube forming means, a pair of draw bars for clamping and drawing the wrapper tube from the forming means, a swinging arm comprising a bracket and a pair of parallel rods projecting therefrom, said draw bars being slidably mounted on said rods, means for moving said draw bars on said rods between an open position and a closed position wherein the wrapper tube is clamped in a position aligned with the axis of said tube, linkage means for interconnecting said take-off roll and said swinging arm and moving the take-off roll in the same direction as the arm, and linkage means for mounting said arm and constraining downward movement of said draw bars to a substantially straight vertical path when the draw bars are in their closed position and then returning the draw bars upwardly when they are in their open position, and means for actuating said web brake to grip said web when the draw bars are moved out of their closed position whereby the take-off roll will draw a further length of web from the supply roll as the swinging arm moves upwardly and the supply roll brake maintains the web in a controlled path.

54. In a packaging machine having fixed frame members, vertically disposed means for a tube of wrapper material, means for mounting a supply roll of wrapper material and leading a web therefrom to the upper end of said forming means, a take-off roll between said supply roll and said forming means around which the web is trained in an inverted loop, a web brake engageable with said web between said take-off roll and said tube forming means, a pair of draw bars for clamping and drawing the wrapper tube from the forming means, a swinging arm comprising a bracket and a pair of parallel rods projecting therefrom, said draw bars being slidably mounted on said rods, means for moving said draw bars on said rods between an open position and a closed position wherein the wrapper tube is clamped in a position aligned with the axis of said tube, linkage means for mounting said arm and constraining downward movement of said draw bars to a substantially straight vertical path, said linkage means comprising a pair of links pivotally connected to opposed frame members above said swinging arm and connected at their lower ends to said bracket adjacent the rear thereof, and a second pair of links pivotally connected at one end to said frame members and at their other ends to the forward portion of said bracket whereby an intermediate portion of said bracket will move in a vertical direction approximately half the distance of the downward movement of said draw bars, a pair of links connecting opposite ends of said take-off roll to said intermediate bracket portion, said swinging arm linkage mechanism further constraining movement of said draw bars to an upward direction when the draw bars are in their open position, and means for actuating said web brake to grip said web when the draw bars are moved out of their closed position whereupon the take-off roll will draw a further length of web from the supply roll as the swinging arm moves

upwardly, said length of web approximating the length of package being formed.

55. In a packaging machine having fixed frame members, vertically disposed means for forming a tube of wrapper material, means for mounting a supply roll of wrapper material and leading a web therefrom to the upper end of said forming means, a take-off roll between said supply roll and said forming means around which the web is trained in an inverted loop, a web brake engageable with said web between said take-off roll and said tube forming means, a pair of draw bars for clamping and drawing the wrapper tube from the forming means, a swinging arm comprising a bracket and a pair of parallel rods projecting therefrom, said draw bars being slidably mounted on said rods, means for moving said draw bars on said rods between an open position and a closed position wherein the wrapper tube is clamped in a position aligned with the axis of said tube, linkage means for mounting said arm and constraining downward movement of said draw bars into a substantially straight vertical path, said linkage means comprising a pair of links pivotally connected to opposed frame members above said swinging arm and connected at their lower ends to said bracket adjacent the rear thereof, and a second pair of links pivotally connected at one end to said frame members and at their other ends to the front portion of said bracket whereby an intermediate portion of said bracket will move in a vertical direction approximately half the distance of the downward movement of said draw bars, a pair of links connecting opposite ends of said take-off roll to said intermediate bracket portion, a tension spring connected to each end of said take-off roll and extending upwardly and connected thereabove to a frame member of the machine, said tension spring serving to guide the take-off roll upwardly and also counterbalancing the weight of said swinging arm and draw bars, said swinging arm linkage mechanism further constraining movement of said draw bars to an upward direction when the draw bars are in their open position, and means for actuating said web brake to clamp said web when the draw bars are moved out of their closed position whereupon the take-off roll will draw a further length of web from the supply roll as the swinging arm moves upwardly, said length of web approximating the length of package being wrapped.

56. In a packaging machine, vertically disposed means for forming a tube of wrapper material, means for mounting a supply roll of wrapper material and leading a web therefrom to the upper end of said forming means, a pair of draw bars for clamping and drawing the wrapper tube from the forming means, a swinging arm comprising a bracket and parallel rods projecting therefrom, said draw bars being slidably mounted on said rods, means for moving said draw bars on said rods between an open position and a closed position wherein the wrapper tube is clamped in a position aligned with the axis of said tube, linkage means including a pivotal connection adjacent the rear of said bracket for mounting said arm and constraining downward movement of said draw bars to a substantially straight vertical path when the draw bars are in their closed position, and counter-balancing means tending to rotate said bracket about said pivotal connection in a direction opposite the weight of said swinging arm and draw bars, thereby minimizing the amount of power needed to move the draw bars up and down.

57. In a packaging machine, means for mounting a supply roll of wrapper material and drawing a web therefrom, a supply roll brake comprising a slackener roll around which the web is looped, a pair of arms pivotally mounted adjacent the supply roll axis with the slackener roll journaled at the ends thereof, a control lever having a curve cam path formed thereon eccentrically of the axis of said arms, a member projecting from one of said arms and engageable with said cam track, a brake drum rotatable with said supply roll, a brake member mounted on said lever and engageable with said drum, the eccentricity of said cam path being such that as the loop around the slackener roll decreases the brake is gradually disengaged from said brake drum as the slackener roll is progressively swung about its pivotal axis.

58. In a packaging machine, means for mounting a supply roll of wrapper material and drawing a web intermittently therefrom, a supply roll brake comprising a slackener roll about which the web is looped, a pair of arms pivotally mounted adjacent the supply roll axis with the slackener roll journaled adjacent the outer ends thereof, a control lever having a curved plate secured thereto and disposed eccentrically of the axis of the said arms, a follower projecting from one of said arms and engageable with said curved plate, spring means connected to said arms and tending to increase the loop formed around said slackener roll, a brake drum rotatable with said supply roll, a brake member mounted on said lever and engageable with said drum, the eccentricity of said curved plate being such that as the loop around the slackener roll decreases the brake member is gradually disengaged from said brake drum as the slackener roll is progressively swung about said pivotal axis.

59. In a packaging machine, means for mounting a supply roll of wrapper material and drawing a web intermittently therefrom, a supply roll brake comprising a slackener roll about which the web is looped, a pair of arms pivotally mounted adjacent the supply roll axis with the slackener roll journaled adjacent the outer ends thereof, a control lever having a curved plate secured thereto and disposed eccentrically of the axis of the said arms, a follower projecting from one of said arms and engageable with said curved plate, spring means connected to said arms and tending to increase the loop formed around said slackener roll, a brake drum rotatable with said supply roll, a brake member mounted on said lever and engageable with said drum, the eccentricity of said curved plate being such that as the loop around the slackener roll decreases the brake member is gradually disengaged from said brake drum as the slackener roll is progressively swung about said pivotal axis.

20 60. In a packaging machine, means for mounting a supply roll of wrapper material and drawing a web intermittently therefrom, a supply roll brake comprising a slackener roll about which the web is looped, a pair of arms pivotally mounted adjacent the supply roll axis with the slackener roll journaled adjacent the outer ends thereof, a control lever having a curved plate secured thereto and disposed eccentrically of the axis of the said arms, a follower projecting from one of said arms and engageable with said curved plate, spring means connected to said arms and tending to increase the loop formed around said slackener roll, a brake drum rotatable with said supply roll, a brake member mounted on said lever and engageable with said drum, the eccentricity of said curved plate being such that as the loop around the slackener roll decreases against the action of said first spring means, the brake member is gradually disengaged from said brake drum as the slackener roll is progressively swung about said pivotal axis in response to a pull on said web, and means engaged by said arms for limiting movement of said arms in a direction increasing 25 the loop formed around said slackener roll, said control lever being in a position wherein full braking force is applied to said drum when said arms engage said limiting means.

30 61. In a packaging machine, means for mounting a supply roll of wrapper material secured in place on a shaft, said mounting means comprising an upwardly open journal for receiving each end of said shaft, a pair of idler rolls spaced outwardly from said supply roll and above said shaft, a slackener roll disposed beneath said 35 idler rolls whereby a web may be drawn from said supply roll and then a loop formed around said slackener roll as the web passes over the idler rolls, a pair of arms pivotally mounted on a common axis parallel to the axis of the shaft and spaced therebeneath, said arms projecting outwardly and pivotally receiving said slackener roll, a spring connected to each of said arms and urging said arms downwardly to increase the length of loop formed around said slackener roll, a brake drum secured to said 40 shaft, a control lever pivotally mounted at a point spaced above said shaft and depending therebelow to one side thereof, a brake member mounted on said lever and engageable with said drum, a curved plate adjustably secured to said control lever in eccentric relation to the pivotal axis of said arms, a follower mounted on one of said arms and engageable with said curved plate, the eccentricity of said curved plate being such that as the loop around the slackener roll decreases in response to a pull on the web the brake member is gradually disengaged 45 from said brake drum as the slackener roll is progressively 50 55 60 65 70 75

swung about said pivotal axis, a fixed member limiting downward movement of said arms and thereby limiting the length of loop formed around said slackener roll, and spring means connected to said control lever and urging said brake into engagement with said brake drum, said stop means being effective in a position wherein full braking force is applied to said drum.

61. In a packaging machine, vertically disposed means for forming a tube of wrapper material, means for mounting a supply roll of wrapper material and leading a web therefrom to the upper end of said tube forming means, a pair of draw bars for clamping and drawing the wrapper tube from the forming means, an arm extending laterally of the wrapper tube and on which the draw bars are directly mounted adjacent one end thereof, means for moving said draw bars relative to said arm between an open position and a closed position wherein the wrapper tube is clamped in a position aligned with the axis of said tube, and spring means secured to said swinging arm and effective in an upward direction to counterbalance the weight of said arm and draw bars, thereby minimizing the power required to move the draw bars up and down.

62. In a packaging machine, vertically disposed means for forming a tube of wrapper material, means for mounting a supply roll of wrapper material and leading a web therefrom to the upper end of said forming means, a pair of draw bars, means for clamping the draw bars against the wrapper tube and drawing it downwardly from the end of said forming means and then opening said draw bars to release said wrapper tube and then moving said draw bars upwardly towards said forming means preparatory to again clamping the wrapper tube, characterized by the provision of a take-off roll between said supply roll and said former and around which the web is trained in an inverted loop, linkage means interconnecting said take-off roll and said draw bars and moving the take-off roll in the same direction as said draw bars whereby the take-off roll will draw a further length of web from the supply roll as the draw bars move upwardly.

63. Apparatus as in claim 62 wherein means are provided for clamping the web between the take-off roll and the lower end of the former to insure that a length of web will be drawn from the supply roll as the draw bars move upwardly.

64. In a packaging machine, means for forming a tube of wrapper material, means for mounting a supply of wrapper material and leading a web therefrom to said forming means, a pair of draw bars for clamping and drawing the wrapper tube from the forming means, an arm extending laterally of the wrapper tube and on which the draw bars are directly mounted adjacent one end thereof, means for moving said draw bars relative to said arm between an open position and a closed position wherein the wrapper tube is clamped in alignment with the axis of said wrapper tube, means directly connected to the other end of said arm for mounting said arm for movement of said draw bars along a substantially straight path outwardly of said forming means when the draw bars are in their closed position, and for return movement of the draw bars toward said forming means when the draw bars are in their open position and means for so moving the arm.

65. In a packaging machine, means for forming a tube of wrapper material, means for mounting a supply of wrapper material and leading a web therefrom to said forming means, a pair of draw bars for clamping and drawing the wrapper tube from the forming means, an arm extending laterally of the wrapper tube and on which the draw bars are directly mounted adjacent one end thereof, means mounted on said arm for moving said draw bars relative to said arm between an open position and a closed position wherein the wrapper tube is clamped in alignment with the axis of said wrapper tube, means directly connected to the other end of said arm for mount-

ing said arm for movement of said draw bars along a substantially straight path outwardly of said forming means when the draw bars are in their closed position and for return movement of the draw bars towards said forming means when the draw bars are in their open position, and means for so moving the arm.

66. In a packaging machine, means for forming a tube of wrapper material, means for mounting a supply of wrapper material and leading a web therefrom to said forming means, a pair of draw bars for clamping and drawing the wrapper tube from said forming means, an arm extending laterally of the wrapper tube and on which the draw bars are mounted, means for moving said draw bars between an open position and a closed position in which the wrapper tube is gripped therebetween and linkage means pivotally mounting said arm and constraining movement of said draw bars to a substantially straight line path outwardly of said forming means when the draw bars are in their closed position, and returning the draw bars towards said forming means when the draw bars are in their open position, and means for moving said arm to obtain the prescribed movement of said draw bars.

67. In a packaging machine, means for forming a tube of wrapper material, means for mounting a supply of wrapper material and leading a web therefrom to said forming means, a pair of draw bars, linkage means supporting said draw bars for longitudinal movement towards and away from said forming means, said draw bars being movable relative to said linkage means between an open position and a closed position in which the wrapper tube is gripped therebetween, said linkage means constraining the longitudinal movement of said draw bars outwardly of said forming means to a substantially straight line path when the draw bars are in their closed position.

68. In a packaging machine, means for forming a tube of wrapper material, means for mounting a supply of wrapper material and leading a web therefrom to said forming means, linkage means supporting said draw bars for longitudinal movement towards and away from said forming means, and means mounted on said linkage means for moving said draw bars relative to said linkage means between an open position and a closed position in which the wrapper tube is gripped therebetween, said linkage means constraining the longitudinal movement of said draw bars away from said forming means to a substantially straight line path when the draw bars are in their closed position.

69. In a packaging machine, means for forming a tube of wrapper material, means for mounting a supply of wrapper material and leading a web therefrom to said forming means, a pair of draw bars for gripping and heat sealing the tube of wrapper material, linkage means supporting said draw bars for longitudinal movement towards and away from said forming means, means mounted on said linkage means for moving said draw bars relative to said linkage means between an open position and a closed heat sealing position in which the wrapper tube is gripped therebetween, said linkage means constraining the longitudinal movement of said draw bars away from said forming means to a substantially straight line path when the draw bars are in their closed position, means mounted on one of said draw bars for transversely severing the tube intermediate the area heat sealed by said draw bars, and means mounted on one of said draw bars for operating said severing means.

70. In a packaging machine, means for forming a tube of wrapper material, means for mounting a supply of wrapper material and leading a web therefrom to said forming means, a pair of draw bars for gripping and heat sealing the tube of wrapper material, linkage means supporting said draw bars for longitudinal movement towards and away from said forming means, means mounted on said linkage means for moving said draw bars relative to said linkage means between an open position and a closed heat sealing position in which the wrapper tube is

gripped therebetween, said linkage means constraining the longitudinal movement of said draw bars away from said forming means to a substantially straight line path when the draw bars are in their closed position, means including a knife having an interrupted edge and mounted on one of said draw bars for severing the wrapper tube intermediate the area heat sealed by said draw bars, means mounted on one of said draw bars for operating said severing means to sever said tube and optional means for limiting said operating means so that the tube is pierced by the interrupted edge of said knife and the knife is prevented from completely severing the tube thereby forming perforations in said tube intermediate the heat sealed area.

71. In a packaging machine, means for forming a tube of wrapper material, means for mounting a supply of wrapper material and leading a web therefrom to said forming means, a pair of draw bars, linkage means supporting said draw bars for longitudinal movement towards and away from said forming means, means mounted on said linkage means for moving said draw bars relative to said linkage means between an open position and a closed position in which the wrapper tube is gripped therebetween, said linkage means constraining the longitudinal movement of said draw bars away from said forming means to a substantially straight line path when the draw bars are in their closed position, means for adjusting the stroke of the longitudinal movement of said draw bars, and means for adjusting the rate of said longitudinal movement.

72. In a packaging machine, means for forming a tube of wrapper material, means for mounting a supply of wrapper material and leading a web therefrom to said forming means, a pair of draw bars, linkage means supporting said draw bars for longitudinal movement towards and away from said forming means, means mounted on said linkage means for moving said draw bars relative to said linkage means between an open position and a closed gripping position, means for adjusting the extent of movement of said draw bars between their open and closed positions, said linkage means constraining the longitudinal movement of said draw bars away from said forming means to a substantially straight line path when the draw bars are in their closed position, means for adjusting the stroke of the longitudinal movement of said draw bars, and means for adjusting the rate of said longitudinal movement.

73. In a packaging machine, means for forming a tube of wrapper material, means for mounting a supply of wrapper material and leading a web therefrom to said forming means, a pair of draw bars, an arm on which the draw bars are slidably mounted, means mounted on said arm for moving said draw bars between an open position

and a closed position in which the wrapper tube is gripped therebetween and linkage means for mounting said arm for longitudinal movement of said draw bars along a substantially straight line path outwardly of said forming means when the draw bars are in their closed position.

74. In a packaging machine, means for forming a tube of wrapper material, means for mounting a supply of wrapper material and leading a web therefrom to said forming means, a pair of draw bars, an arm disposed generally laterally of said wrapper tube, a pair of rods projecting from said arm and embracing said wrapper tube, said draw bars being slidably mounted on said rods, means for moving said draw bars between an open position and a closed position in which the wrapper tube is gripped therebetween, and means including a connection to said arm for moving the draw bars longitudinally towards and away from said forming means, and constraining movement of said draw bars to at least a substantially straight line path as they are moved away from said forming means when they are in their closed position.

75. A combination as in claim 74 wherein the draw bars are disconnectably coupled to the opening and closing means and are free to pass over the ends of the rods when disconnected to permit ready replacement or repair of the draw bars.

76. A combination as in claim 74 wherein the means for moving the draw bars between open and closed positions comprise a double-ended lever pivotally mounted on said arm, a link connecting one end of the lever and one draw bar, a second link connecting the other end of said lever and the other of said draw bars and means for oscillating said lever to so move the draw bars on said rods.

77. A combination as in claim 76 wherein the points of connection between the links and the double-ended lever are in substantial alignment with the draw bars when the draw bars are in their closed position.
